BUNDLE BINDING AND TYING MACHINE

James Marshall Leaver, Jr., Oakland, Calif.

Application February 21, 1921, Serial No. 446,942

94 Claims. (Cl. 100—31)

This invention relates to machines for binding bundles, boxes, and the like.

The invention relates to bundle binding machines in which a band is drawn from a source of supply, tensioned and maintained under tension, and wrapped and secured taut about a bundle which may be considered to consist of a number of articles of like kind assembled together, a box, or any kind of a package or bundle of various dimensions within the bundle receiving capacity of the machine, without dragging the band across any corner or face thereof, and without the requirement of mechanically translating the bundle from one position in the machine to another position in the machine for the binding thereof.

For the purpose of brevity, the term "bundle" is used in the specification and claims and it is to be understood that the same comprehends the foregoing recited objects or any kind of an object to be bound.

Inasmuch as this invention discloses many original and useful features of marked departure from the practice and showing of the prior art, and which features, by reason of their novelty, it is believed may be best understood by recital of some of the objects of the invention preliminary to the reading of that part of the specification relating to the disclosure of the drawings, the following introductory objects are recited with the understanding that the language of said recited objects is not to be construed as embracing the extent or the scope of the invention and it is also to be understood that other objects of the invention are to be found in the further reading of the specification and the showing of the drawings.

Although my invention is herewith illustrated and described in connection with a form of bundle binding machine using wire as a banding element, it will be apparent that the invention is basic and primary in many respects, and is desirable and adaptable for use in connection with other forms of binding machines using any suitable binding material, and I intend to claim the same broadly and in the fullest scope in the appended claims.

An object of the invention is to provide a machine which is readily adjustable for all conditions of service in the binding of bundles manually located in binding position, without dragging the binding element across the material or corners of the bundle, and which is capable of binding either compressible or incompressible bundles.

Another object of the invention is to provide a machine which will place one or more bands

under tension at desired points about a bundle manually located in binding position, and secure the ends of the same.

Another object of the invention is to provide a machine which is capable of binding and tying a plurality of bundles manually located in binding position, at the one time.

Another object of the invention is to furnish a machine with a bundle binding mechanism which will convexly tension and place a band under predetermined tension about a bundle, or the like, manually located in binding position, regardless of the size of the same within the bundle receiving capacity of the machine.

Another object of the invention is to provide a machine with novel and useful simplified features of construction, and mechanical apparatus such as provides increased capacity in the binding and securing of bands about bundles and renders such machine particularly suitable to the varying and exacting requirements of all branches of the bundle binding trade.

Another object of the invention is to provide a machine which is capable of completely banding and securing a tensioned band about a bundle manually located in binding position, in such manner that the same tightly and securely embraces and maintains the bundle firm and compact, thereby conserving space, and preventing loss of contents thereof, by reason of pilferage, or shrinkage, or breakage, or damage due to handling, transportation, warehousing etc.

Another object of the invention is to provide a machine which will convexly tension and tightly bind and secure a metallic band about a box, shipping case, crate or container manually located in binding position, whereby the tightly applied and secured band will reinforce the same to such extent that lighter material may be used in the construction of said box, shipping case, crate or container, and a considerable saving in material cost effected.

Another object of the invention is to provide a bundle binding mechanism capable of wrapping a band entirely around a bundle without sliding it across any corner of the bundle and disposing initial and terminal portions thereof in overlapped relation within band uniting mechanism, whereby actuation of the uniting mechanism results in securing the wrapped band about the bundle.

Another object of the invention is to provide a bundle binding mechanism capable of wrapping a tensioned band completely about a bundle and for disposing initial and terminal portions

thereof in overlying or overlapping relation within the slot of a rotary twister disposed in band receiving register in the plane in which the band is wrapped, whereby rotation of the twister results 5 in intertwisting the portions to secure the band about the bundle.

Another object of the invention is to provide a band wrapping mechanism operative to pass a band twice in the same plane within band uniting mechanism and into overlying relation therein, during each cycle of movement of said band wrapping mechanism.

Another object of the invention is to provide a band wrapping mechanism operative to pass a wire twice into tying register through and within the slot of a rotary wire twister in register with the plane of movement of the wire, during each cycle of movement of said band wrapping mechanism.

20 Another object of the invention is to provide a band wrapping mechanism operative alternately in clockwise and counter-clockwise directions and adapted during each cycle of movement thereof to pass a wire twice through and within the narrow slot of a slotted twister disposed in wire receiving register in the plane in which the wire is wrapped or passed.

Another object of the invention is to provide a band wrapping mechanism operative to provide a 30 lead section of a tensioned band below the plane of supporting a bundle and to pass the band twice within band uniting mechanism during each cycle of movement of said band wrapping mechanism.

Another object of the invention is to provide a 35 bundle binding mechanism capable of movement first in one direction and then in the other during each cycle of movement thereof to first wrap a binding element completely about a bundle and to then retract a newly gripped lead section of the element from its position at the completion of 40 the binding of the bundle to another position from which the element is more readily applicable to another bundle in the succeeding cycle of movement of said mechanism.

45 Another object of the invention is the provision of a novel and useful bundle binding mechanism movable in clockwise and counter-clockwise directions in a circular path of travel and having a plurality of lead-off band applying and guiding means coadjacently and cooperatively mounted 50 in respective band guiding positions whereby the lead of the band transfers or disengages from one of said guide means and is engaged and convexly tensioned and wrapped about the bundle by the other of said guide means during each cycle 55 of operation of the binding mechanism.

Another object of the invention is the provision 60 of novel means for reversing and actuating the bundle binding mechanism whereby said mechanism receives controlled actuation in clockwise and counter-clockwise directions during each cycle of operation thereof.

Another object of the invention is to provide a 65 gripping mechanism for compensatingly and firmly gripping the end of a binding element without the requirement of substituting a part or parts of said gripping mechanism when the size or gage of the binding element varies within the limit of yieldability of said mechanism.

70 Another object of the invention is to provide 75 novel bundle supporting and positioning means whereby a bundle may be located in proper binding position on the support irrespective of the width of the bundle within the bundle receiving

Another object of the invention is to provide a novel bundle clamp and actuating mechanism therefor whereby a bundle is compensatingly and firmly clamped on the support in such manner as to prevent injury to the material of the bundle or the machine irrespective of the size of the bundle within the limit of yieldability of the clamp. 5

Another object of the invention is to provide a machine wherein bundle moving mechanism is 10 operative after the binding and securing of a band about a bundle for moving the bound bundle in a horizontal plane out of the position in which it was bound and secured and through the machine. 15

Another object is to provide means for gripping the lead of the wire at the end of its movement around a bundle and through the tying means in one direction, and for passing the wire through the tying means in the opposite direction 20 whereby the wire is bent over the gripping means.

The invention will be best understood from a consideration of the following detailed description taken in connection with the accompanying drawings forming part of this specification, with the understanding, however, that the invention is not confined to any strict conformity with the showing in the drawings, but may be changed and modified so long as such changes and modifications mark no material departure from the salient 25 features of the invention as expressed in the appended claims. 30

In the drawings:—

Fig. 1 is a front elevation of a machine constituting an embodiment of the invention. 35

Fig. 2 is a side elevation of the same.

Fig. 2^a is a detail view of the bundle clamping mechanism showing the bundle clamped.

Fig. 3 is a central vertical sectional view.

Fig. 4 is a top plan view omitting certain of the mechanism for greater clearness. 40

Fig. 5 is a fragmentary view on an enlarged scale showing the bundle conveying means, the bundle abutment and the releasing means therefor.

Fig. 5^a is an elevation of the conveyer drive gear. 45

Fig. 6 is a fragmentary sectional view taken at right angles to Fig. 5 and illustrating portions of the bundle clamping means as well as of the bundle abutment releasing means. 50

Fig. 7 is a detail view of the upper end of the abutment bar and adjacent parts.

Fig. 8 is a detail of the wire guiding wheels provided on the machine frame.

Fig. 9 is a view showing the knotter mechanism and a slightly modified form of the carrier member adapted to accommodate a modified relation of the wire wrapping means whereby the wire has transferred from one of said means to another of said means during the movement of said means from the position shown in Fig. 2 for wrapping the wire into the knotter mechanism. 55

Fig. 10 is an elevation of the knotter mechanism looking from the left hand side of Fig. 9 and showing the knot completed and the wire end gripped. 60

Fig. 11 is a similar view showing the position of the wire after the bundle has been moved and the bundle binding device has reversed its direction of movement to provide the initial tie strand 65 of wire within the slot of the twister preparatory to wrapping a wire about the bundle.

Fig. 12 is a top plan view of the knotter mechanism.

Fig. 13 is a plan of the gear which drives the 70

knotter mechanism, showing the wire cutter or knife.

Fig. 14 is a plan view illustrating the wire tensioning and slack take-up device.

5 Fig. 15 is a detail view in section illustrating the adjustable crowding wheel on the free end of the wire tensioning arm.

Fig. 15a is a similar view illustrating the mounting of the outermost wheel on said arm.

10 Fig. 16 is a diagrammatic view illustrating the curvilinear path of travel of the binding means about a bundle positioned within the area defined by the movement of said means, that surface within the dotted curvilinear path of travel of the 10 binding pulleys 94 and 95 and the horizontal plane of the bundle support being the area referred to in the claims and specification. This view also illustrates the movement of the binding apparatus about a stationary bundle positioned on the support within the radius of its path of travel.

15 Fig. 17 is a front elevation of a machine capable of placing two bands simultaneously about a bundle at the desired points, some of the frame parts being omitted for clearness.

20 Fig. 18 is a similar view of a machine capable of handling two bundles of different dimensions simultaneously and adapted to bind and tie each bundle with a single band, the machine frame and distant parts being omitted.

25 The machine of the present invention is fundamentally designed to bind bundles in the position in which they are manually located for binding, provision being made for the clamping of the bundles so located during the initial wrapping movement of the binder. Being so designed, it is 30 readily distinguishable from that class of machines in which bundles are mechanically translated from bundle receiving position to bundle binding position.

30 The form of machine herein illustrated and described is constructed to draw wire from a coil, place the wire under tension and pass it around a bundle or box, which is preferably compressibly held, and secure the wire taut around the bundle or box; it will be understood that the wire is sometimes designated "a tie wire", and when encircled about the bundle, "a tie". It provides an oscillatory bundle binding mechanism movable in an arcuate path for wrapping a wire completely 40 about a bundle without dragging the same across any face or corner of the bundle, and a knotter mechanism, including a slotted twisting device, disposed intermediate spaced fixed bundle supporting elements, into the slot of which twisting device initial and terminal portions of the wire are introduced directly by the bundle binding mechanism. The bundle binding mechanism is provided with a plurality of wire guide means which maintain the feed of the wire free of contact with 50 the bundle during the wrapping of the wire thereabout, and a lead-off member consisting of a pair of wire guides mounted in respective band guiding positions whereby during movement of the bundle binding mechanism the wire is directed into the slot of the twisting device around the bundle and again into the slot of said device, the lead of the wire transferring or disengaging from one of said guides and being directed or engaged by the other of said guides during the initial movement of said 60 mechanism. Means adjustable toward and from the knotter mechanism are provided for locating a bundle in proper binding and tying position on the bundle supporting elements. The wire, while in tension, is automatically gripped adjacent the twisting device, then wrapped by the bundle bind-

ing mechanism into the slot thereof and a sufficient distance around a bundle to completely bind the bundle and overlap the portion of the wire within said slot, whereby rotation of the twisting device intertwistingly unites the portions 5 therein to secure the encircled wire taut about the bundle. Means are then provided for cutting the united wire free from the strand of wire leading from the coil and for ejecting the united portions from the twisting device and moving the bound 10 bundle out of the machine. The twisting device is arranged with its slot facing away from and at right angles to one face of the bundle so that the wire is introduced therewith twice during each cycle of movement of the bundle binding mechanism. After the uniting of the overlapped portions of the wire, the lead of the wire extending from the united portions to the bundle binding mechanism is gripped and cut free from the bundle and the united portions are released as the 15 bound bundle is automatically moved away from the twisting device and out of the machine. The bundle binding mechanism is operative alternately in clockwise and counter-clockwise directions about an axis passing through the bundle, 20 and in one direction of movement thereof convexly tensions and wraps the wire completely around the bundle tightly against three faces thereof, and in the opposite direction of movement retracts and guides a newly gripped lead 25 section from its position at the completion of the binding of the bundle to another position from which the wire is more readily applicable to another bundle in the succeeding cycle of movement 30 of said mechanism. Reversal of movement of the bundle binding mechanism causes the wire to be bent around the gripper, thus greatly increasing the holding effect of the gripper and permitting the wire to be held under high tension, and also provides the initial tie portion of the wire within 35 the twisting device. Said reversal of movement also provides for the arranging of a lead section of the wire below the plane of the bundle support for ready and quick application to the lower face of the bundle during each cycle of operation of 40 the bundle binding mechanism. Means are provided for delivering the wire under predetermined tension and for maintaining the wire leading to the bundle binding mechanism and the gripping device in tension during the clockwise and counter-clockwise directions of movement of the bundle binding mechanism, said means being responsive to variable tension on the wire. Means are embodied for timing and controlling the operation 45 of the bundle binding mechanism and the bundle 50 clamp, and for timing and controlling the operation of the twisting device, the cutter, the gripper, and the means for ejecting the united portions of the wire and moving the bound bundle out of the machine. Other features of construction and 55 operation are disclosed and will become apparent 60 as the specification proceeds.

The numeral 19 designates the base of the machine, which is supported by casters 11. A frame 12 rises vertically from the ends of the base 10, 65 and at intervals, as will be described, transversely extending connecting rods join the frames together so that a rigid unitary frame structure is provided upon which the working parts may be supported. Upon the base of the machine an 70 electric motor 13 is set, this motor having a pinion 14 meshing with the main drive gear 15. Instead of employing a self-contained power unit, the machine may be driven by a belt, or in any other manner. A clutch 16 is interposed between 75

the main drive gear 15 and the main drive shaft 20. This clutch, which is operated by a connecting element 17 and a foot lever 18 pivoted at 19 upon the frame, is of the type which permits but 5 one revolution of the main drive shaft at a time and thereafter automatically disengages the shaft from its drive gear. One form of such a clutch is described in detail in a co-pending application filed by me May 10, 1920, Serial No. 380,375, and 10 is shown particularly in Figs. 15 to 20, inclusive, of the drawings forming a part of said application.

The main drive shaft 20 is journaled at its 15 opposite ends in the frames 12. The end of the shaft remote from the drive gear 15 carries a combined cam and intermittent drive gear element 21, best seen in Fig. 3. This element is preferably in the form of a circular flat plate whose periphery is smooth and unbroken except for a small section thereof where gear teeth 22 are provided. 20 These gear teeth, as indicated, project only partly beyond the periphery and the arcuate extent of these teeth may approximate a quadrant. One side face of element 21 has a cam groove 26 formed therein and this cam groove has an arcuate part 25 concentric with the shaft 20, constituting a rest portion approximating 180 degrees. The remainder of the cam groove 26 is designed so as to give an oscillating motion to the follower element toward and from the center of the cam, with a short 30 rest portion 26a interposed between the portions which cause the oscillation of the follower. By reference to Fig. 3, it will be noted that the cam groove 26 is so formed and designed that it imparts shockless and gradually accelerating movement to the lever 27, and its connecting features 35 hereinafter described.

A lever 27 is pivoted upon a bracket 29 secured to the machine frame and carries a roller 28 running in the cam groove 26. The free end of the 40 lever 27 is pivotally joined to a connecting link 30 having a length nearly equal to the height of the machine. The upper end of link 30 is pivotally connected, as at 32, to an extension arm 34 rigid with a quadrant gear 33, which is pivoted, as at 45 33a, upon the machine frame. From the foregoing description, it will be clear that each revolution of element 21 causes swinging of lever 27 toward and from the center of cam 21 and consequently the swinging of the quadrant gear 33 50 through an arc. The two extreme positions of the quadrant gear 33 are illustrated in Figs. 2 and 3, the position of Fig. 2 being the normal position, when the machine is at rest, and at the start and finish of the cycle of operations. 55 Referring to Figs. 2 and 3, it will be noted that the construction of the rotary element 21 is such that said element actuates the respective actuating elements 23 and 27, in controlled and timed relation thereby serving as a single element adapted to perform the aforesaid functions.

The quadrant gear 33 meshes with a gear 34 secured to one end of a countershaft 35. As seen in Fig. 4, this countershaft extends for a distance less than half the length of the machine. The 60 quadrant gear 33 and the gear 34, constitute rack and pinion mechanism designed to effect oscillation and reversal of movement. Also secured to this shaft is a link 36 pivotally connected at its extremity to the upper end of an oscillatory or 65 reversing mounting member 38 and which member is oscillated and reversed by the rack and pinion mechanism 33 and 34. A similar link 37 is pivoted, as at 37a, upon an auxiliary frame 41 (Fig. 3) intermediate the ends of the machine and supported by a plurality of upper and lower frame 70

connecting rods 39, 40. The other end of link 37 is pivotally connected to the member 38 at an intermediate point. The links 36 and 37 are of exactly the same length, and the arrangement is such that the links 36, 37 form a parallel motion linkage for the member 38 whereby the member 38 is maintained vertical at all times and is moved forwardly in a circular path in a medial vertical plane and vice versa when the gear 34 is rotated by the quadrant gear 33. The disposition of the auxiliary frame 41 is such that the member 38 moves in a vertical plane preferably midway between the ends of the machine; and for the type of machine illustrated in Figs. 1 to 16, inclusive, this auxiliary frame is immovable whereby the 15 position of the member 38 relative to the machine ends is unvarying.

From a consideration of the member 38 and its actuating mechanism I will turn to the bundle clamping means. A pair of cams 42 are secured 20 upon the main drive shaft 20, these cams being duplicates. There is an arm 43 provided for each cam 42, each arm carrying a roller 44 adapted to ride upon the edge of the corresponding cam. One end 46 of each arm 43 is pivoted upon a rod 45 extending longitudinally of the machine from end to end, as shown in Figs. 1 and 3. The end 46 is enlarged and as best seen in Fig. 1 has an annular groove 47 into which a stud 49a carried by the lower end of a bar 49 projects. The 30 opposite end of arm 43 is reduced and perforated to fit about an upright rod 51—see Fig. 2a. A coil spring 52 is mounted on the rod 51 at the lower end thereof, which is screw-threaded so that a nut 53 may adjust the tension of the 35 spring 52. The weight of the arm 43 is thrown on the spring 52; and when the cam 42 depresses the arm 43, the spring 52 is compressed as indicated in Fig. 2a. A washer is interposed between the spring 52 and the arm 43, as shown. The 40 spring 52 as seen in Fig. 3 maintains the arm 43 normally in a horizontal position with the roller 44 pressed against the cam 42. The latter is so designed that for approximately three quarters of a revolution the arm 43 is maintained stationary or in the position illustrated in Fig. 3, while for one quarter of a revolution this arm is depressed, as shown in Fig. 2a. The relation of 45 cams 42 and 21 is such that the depression of arm 43 takes place substantially simultaneously 50 with the movement of the member 38 from the position of Fig. 2 to the position of Fig. 3. In other words, the arm 43 is depressed only during the initial movement of the member 38 around the bundle and for a brief period after such movement. As seen in Fig. 3, the cam 42 is so placed that it intercepts the short rest portion 26a of the cam groove 26. This rest portion is where the roller 28 lies when the machine itself is at rest. Thus, as soon as the foot lever 18 is 55 depressed and the clutch thrown in, the arm 43 is moved down in the manner shown and described, and simultaneously with the initial movement of the bundle binding member 38. This depression of arm 43 effects clamping of the 60 bundle as will be described, while the encircling movement of the member 38 encloses the bundle with a binding element. The cams 42 are so designed that they do not immediately release the bundle after the member 38 assumes the 65 position of Fig. 3, but on the contrary gradually release it, whereby, as will be later described, the knotting starts before the clamping means is lifted from the bundle.

The upper end of rod 51 is bifurcated and is 70

pivotedly connected with a guiding bar 54. Each guiding bar 54 is longitudinally slotted as at 60 (Figs. 2 and 5), whereby a bundle clamping bar 61 preferably of angular section may be adjustably secured thereto by bolts 62 or the like. The bundle 63 is partially supported at the two ends thereof upon one-piece guides and supports 55 which extend approximately the entire width of the machine, are in the form of upright frames and may, if desired, be castings. Each support 55 not only upholds the ends of the bundle but also receives a conveyer chain 64 and carries driving mechanism for said chain. The purpose of supporting the bundles at each end thereof as shown in Fig. 1 is primarily for the purpose of steadyng the same during the clamping of the bundle, but it will be understood from Fig. 1 that the central bundle supports will of themselves constitute sufficient support for the bundle.

As best seen in Fig. 6, the intermediate part of the guiding bar 54 is adjacent the guide frames 55 on the outside thereof and each guiding bar is held to the supporting frame, being slideable vertically with respect thereto. A bracket 59 is secured to each support 55 and has a slot for receiving the guiding bar 54. The bracket 59 also provides an abutment for a projection 58 formed integrally with each guiding bar 54. Each support 55 also has a bracket 56 spaced from the projection 58 and a coil spring 57 is interposed between the bracket 56 and projection 58, whereby the latter is normally held against the bracket 59. The spring 57 also serves to maintain the pressure clamping bar 61 normally above the top of the bundles. When arm 43 is moved down by its cam, the spring 52 is compressed, rod 51 and bar 54 move downwardly, spring 57 is compressed, and bar 61 descends upon the bundle top to clamp the bundle upon its support, as seen in Fig. 2^a. By reference to Figs. 2 and 2^a it will be noted that the spring 52 is arranged and adapted to compensate for variations in the sizes of bundles, within the limits of yieldability or compensation of said spring 52, and it will be understood that the effectiveness of said spring as to either the holding or compressing of a bundle is simply a matter of predetermining the degree of yieldability or the force to be applied through the medium of said spring. The spring 52 not only serves to accommodate bundles of varying dimensions and to predetermine the holding or compression of the bundle as may be desired, but it also serves to eliminate breakage of clamping features wherein the clamps are positively driven and have no yieldability with respect to oversized bundles. The clamping features 42, 44 and 57 provide for respectively clamping the bundle and releasing the clamp from the bundle.

With respect to the operativeness of the spring 57, it will be obvious to any mechanic, without a drawing, by reference to Fig. 1, that the projections 56 and 58 may be reversed as to position and thereby the spring 57, would serve to actuate the clamp for clamping the bundle, and with respect to the operativeness of the cam 42, by reference to Fig. 3 it will be likewise obvious that by reversing and placing the elements 43, 44 and 45 above the cam 42 the cam would serve to lift the bar 54 and release the clamping means from the bundle. This is reversing of parts, clearly shown in Figs. 2, 10, 11 and 12 of the applicant's pending application Serial No. 380,375, filed May 10, 1920. The combination of opposed spring action and cam action insures rapid ad-

justable clamping action, and it is to be understood that this combination feature of the invention is not limited to the particular arrangement of said features as disclosed in the drawings.

The means for adjusting the positions of supports 55 will now be described. The bars 49 (Figs. 1 and 3) are secured at their upper ends to the bundle guides and supports 55. Similar bars 50 are secured to the same elements. The lower ends of the bars 50 have studs 50^a fitting in annular grooves 48 provided on extensions of the cams 42. The bundle supports 55 are mounted upon two or more horizontal rods 67 secured to the frame and are themselves horizontal, extending from front to rear of the machine. The rods 67 act as guides for the bundle supports 55. A screw-threaded shaft 68 passes through the two bundle supports 55 engaging with each by means of right and left hand screw threads. One end of the shaft 68 is squared as indicated at 69, Fig. 1, whereby a tool may be applied to that end to effect rotation of the shaft. This rotation causes approach or withdrawal of the two supports 55 with respect to the medial plane 25 of the machine. As previously pointed out, the member 38 moves in this plane. Thus the bundle supports may be accommodated for all lengths of bundles, while the member 38 passes bands around the middle of all bundles placed on the machine irrespective of their length. The provision of the bars 50 causes the cams 42 to follow the bundle supports and be adjusted therewith; likewise the bar 49 causes the arms 43 and connecting mechanism to follow the bundle supports. Thus, turning of shaft 68 causes adjustment of the bundle supporting means, the bundle clamping means; and, as will be described, of the bundle abutment and of the bundle conveying means. The member 38 and the cooperating knoter mechanism, being at all times central of the bundle, need no adjustment.

The bundle supports 55 have races or channels along the edges thereof in which the chains 64 run, as seen in Fig. 6. These chains are thus housed within the bundle supports and do not support the bundle itself. Each chain is driven by a sprocket 66 (Fig. 5) at the rear end of the bundle support 55. An idler sprocket 65 turns at the other end. The sprockets 66 are fast to a shaft 73 which extends the length of the machine. That end of the shaft 73 which is adjacent the intermittent gear 21 carries a spur gear 72 meshing with an intermediate gear 71 carried upon a stub shaft 71^a (Fig. 1). This stub shaft also carries a gear 70 (Fig. 5^a) whose teeth are adapted to mesh with the teeth 22 of the intermittent gear 21. The gear 70, when rotated, thus causes travel of the conveyer chain 64 in the channels provided by the bundle supports. Each chain 64 has two or more lugs 74 fixed thereto (Fig. 5) and adapted to engage with the lower portion of a bound bundle to carry the same out of the machine after binding and tying have been completed. The gear 70, which may be termed the conveyer drive gear, and the intermediate gear 71 are exactly alike in all respects except that the drive gear 70 has some of its teeth missing and in their place a concave block is provided which is adapted to slide over the periphery of the intermittent gear 21. Fig. 5^a shows the construction of the gear 70. The action of the intermittent gear 21 is to hold the conveyer mechanism stationary during approximately three quarters of its revolution.

Then the teeth 22 are brought into engagement with the end of the concave block of the gear 70, whereupon the latter is rotated. The rotation of gear 70 causes movement of the lugs 74 into engagement with the bound bundle to carry the bundle out of the machine; but this does not take place until after the knotting has been completed.

The two bundle supports 55 carry frames 10 which, together with the supports, provide what might be termed a bundle receiving station designed to receive bundles directly into binding and tying position as the bundles are manually forwarded for binding. These frames are three-sided and comprise front and rear parallel up-rights 75, 76 and a horizontal upper member 77 parallel to support 55 which is slotted as at 77^a, longitudinally. As shown in Figs. 1, 2, 3 and 7, an abutment bar 78 is carried by each of these 15 frames. Brackets 79 are secured along the upper horizontal bars 77, and bolts passing through the slots 77^a provide means whereby the positions of the brackets 79 may be adjusted as desired. (See Fig. 7.) Each abutment bar 78 is pivoted 20 at its upper end upon a pin or the like 78^a passing through the bracket 79 and supported thereby. A torsion spring 80 is mounted on this pin and has one end secured to the bracket, while the other end is connected with the abutment 25 bar. The action of this spring is to hold normally each abutment bar in a vertical position, and if the abutment bars are swung out of such a position, they automatically return thereto. A stop 80^a is carried by the bracket 79 and prevents swinging of the abutment bar beyond the vertical position on its return. The abutment bars 78 provide means for locating the bundles in binding and tying position, and it is against these bars that the piles of shocks are thrust 30 for alignment when the bundles of shocks are first placed in the machine. The knotting mechanism, to be described, is located at a fixed point on the machine and the abutment bars 78 are adjustable toward and away from the knotter mechanism according to the width of the bundles, to 35 provide for the placement of the bundles directly into tying location thereagainst. For very narrow bundles the adjustable abutments will adjust to a position close to the knotter mechanism.

This adjustable feature is a modification of the adjustable abutment feature disclosed in my pending application, Serial No. 380,375, filed May 10, 1920. It was previously stated that the clamping bars 61 are adjustable vertically to 40 provide for clamping bundles of varying heights, and it has also been pointed out that the bundle supports and associated mechanisms are movable longitudinally of the machine to provide for bundles of varying length.

Each of the abutment bars 78 is normally held locked in vertical position by a latch 83 engaging with the reduced and bent end 81 of the abutment bar to prevent movement thereof during placement of the bundle thereagainst and 45 during the binding thereof (see Fig. 5). The latch 83 is secured upon a counterbalanced depression bar 82 by means of a screw or the like passing through a slot 84 provided in the latch; thus the position of the latch piece 83 longitudinally of the depression bar may be adjusted so 50 that it will engage nicely with the end 81. The depression bar 82 is pivotally connected with two counterbalancing elements 85 in the nature of weights, each of which is pivoted as at 86 upon the bundle support 55. The action of the weights 55

85 is to tend to move the bar 82 with its latch piece 83 upwardly toward the top of the bundle supports 55. The rear end of each depression bar 82 has an offset 82^a. A gravity-actuated locking trip 87 is pivoted as at 89 on each bundle support 55 above the offset 82^a. One end of the trip 87 is squared while the other end is beveled as indicated at 88.

As shown in Fig. 6, each depression bar 82 carries a spindle 90 extending through a cutaway 10 portion 91 in the bundle support 55 and carrying at its outer end a roller 92. This roller is engaged by the projection 58 of the guide bar 54, which prevents the bar 82 from rising above the full line position illustrated in Figs. 5 and 6. 15 When the guide bar is forced down the projection 58 engages the roller 92, thereby depressing the counterbalanced bar 82. When the latter is depressed, it swings downwardly and to the right, as viewed in Fig. 5, the counterbalance elements 20 85 providing in effect a parallel motion linkage so that the depression bar 82 is at all times horizontal. Thus the latch-piece 83 is carried out of engagement with the end 81 of the abutment bar so that the latter is free to swing upwardly as shown in dotted lines in Fig. 5. When this depression takes place, the gravity trip 87 falls into the dotted line position indicated in Fig. 5 and the depression bar is maintained by the gravity trip in the dotted line position until the 30 bundle 63 is moved out of the machine by the conveyer. As the bundle is forced out, it strikes the beveled end 88 of the trip 87, moving the same into the full line position of Fig. 5, whereupon the counterbalances 85 restore the depression bar 82 to its normal upper position. The outgoing bundle encounters the abutment bars 78 which previously were released and swings them upwardly against the tension of the springs 89. As soon as the bundle is out of the machine, 40 the springs 80 restore the abutment bars to their vertical position, whereupon their lower ends 81 automatically engage with the latch pieces 83. The stops 80^a insure latching of the ends 81.

The novel bundle binding device, or mechanism, will now be described. Considering Figs. 3 and 9 together, it will be seen that the member 38 may be modified as to form to accommodate novel arrangements of lead-off guide means. In Fig. 3, the member 38 has a straight end section 38^a and an arcuate section 93. The straight end section 38^a carries a lead-off guide pulley or wheel 94, and the arcuate section 93 carries a lead-off guide pulley or wheel 95, the pulley 94 being beneath the pulley 95, which pair of lead-off pulleys may be said to constitute a lead-off member. The arcuate section 93 is provided to enable the lead-off pulleys 94 and 95 to clear and pass beneath the knotter mechanism during movement of the member 38 in its curvilinear path of travel about a bundle. In the construction of Fig. 3, the wire 108 passes between the lead-off pulleys 94 and 95 and said pulleys are so close together that the wire leads off from one or the other according to the position of the member 38. In Fig. 2, the wire may be said to lead off from the upper lead-off pulley 95, but when the member 38 is in the intermediate position—see Fig. 3—the wire will lead from the lower lead-off pulley 94; the run of the wire being at all times in engagement with the lead-off guide pulley 95 in the arrangement of the lead-off guide pulleys shown in said figures. From the showing of Figs. 2, 3, 4 and 16, it is apparent the lead 70 75 80 85 90 95 100 105 110 115 120 125 130 135 140 145 150 155 160 165 170 175 180 185 190 195 200 205 210 215 220 225 230 235 240 of the wire extending from the lead-off pulley 95 to the gripper, hereinafter to be described, transfers from said lead-off pulley to and is engaged and directed by the lead-off pulley 94, or vice versa, according to the direction of movement of the member 38. In the construction of Fig. 9, the pulleys or wheels 94 and 95^a are mounted on the arcuate section 93^a with their axes of rotation determined by the radius of the curvilinear path of movement of the member 38, whereby, during operation of the member 38, the wire disengages from one pulley and is engaged, and directed by the other pulley. From the showing of Figs. 2, 9 and 16, it is apparent that in the normal position of the member 38, and lead-off guide pulleys 94 and 95^a, the wire and lead-off pulley 95^a will occupy a position corresponding to the position of the wire and lead-off pulley 95 in Fig. 2, and that during operation of the member 38, the wire disengages from the pulley 95^a and is engaged and directed by the lead-off pulley 94, or vice versa, according to the direction of movement of the member 38, such disengagement being shown in Fig. 9 wherein the wire 108 (indicated by broken lines) is shown disengaged from the bottom of the groove (indicated by broken line circle) of the lead-off pulley 95^a. Whether the lead-off pulleys are one above the other, as in Fig. 3, or offset as in Fig. 9, the lead of the wire transfers or disengages from one lead-off pulley to the other as the member moves in the arcuate path shown in Fig. 16.

In each instance, the lead-off guide pulley which contacts the lead of the wire upon its transfer or disengagement from the other pulley effects curving or convexly tensioning the wire to cause it to tightly hug three sides of the bundle during movement of the member and the lead-off guide pulleys in their arcuate path of travel about the bundle for wrapping the wire into complete band formation thereabout. By reference to Fig. 3, it will be noted that the lead of the wire has transferred from its lead-off position on the lead-off guide pulley 95, Fig. 2, to the lead-off guide pulley 94, during the operation of the member 38 in its arcuate path of travel from the position of Fig. 2 to the intermediate position of Fig. 3, and it will be understood that in such transfer of the wire the lead off guide pulley 94 engages the same in such manner as to curve or convexly tension the wire in a direction to cause it to press inwardly and tightly against three sides of the bundle, as the wire is wrapped into band formation thereabout. Such curving or convexly tensioning of the wire is accomplished by reversal of direction of movement of the member and lead-off guide pulleys, as is clearly apparent from the disclosure of Figs. 2, 3 and 16, and is of considerable value in the banding of incompressible or relatively incompressible bundles, inasmuch as it eliminates the curving of the wire away from the sides of the bundle and insures tight hugging of the same about the periphery of the bundle. Referring to Figs. 1, 2, 3, 9 and 11, it is seen that the lead-off guide pulleys move in opposite directions in an arcuate path between positions of reversal a sufficient distance to provide and dispose the wire within the knotter mechanism in each direction of their movement, and twice therein during each cycle of movement of said lead-off guide pulleys. Considering Figs. 2, 3, 9 and 16 together, it is seen that the member 38 and lead-off guide pulleys 94 and 95, or 94 and 95^a, in each cycle of movement thereof, move first from the position

of Fig. 2 to the position of Fig. 3, or Fig. 9, to wrap the wire into band formation about the bundle and to extend the same through the knotter mechanism to a position therebeyond for gripping, and then in the opposite direction from the intermediate position of Fig. 3, or Fig. 9, to the normal position of Fig. 2, to retract and arrange the newly gripped lead of the wire to a position from which the same may be more readily and quickly applied about the succeeding bundle. It will be understood by those skilled in the art, that the retracting and arranging of the newly gripped lead of the wire in a position different from that in which the binding of the bundle is completed provides for reduced distance of travel of the member and lead-off guide pulleys in the wrapping of the wire into band formation about the succeeding bundle to be bound and for more ready and quick application of the wire thereabout than is possible in machines having bundle binding members completing their cycle of operation at the position in which the binding of a bundle is completed. As will be evident from Figs. 2, 3 and 9, the position of rest of the member 38 and lead-off guide pulleys 94 and 95, or 94 and 95^a, may be varied by adjustment of the meshing of the teeth of the gear 35 and oscillating quadrant gear 33, and the distance of travel of said member and guide pulleys may be increased or diminished by variation of the size or ratio of said gears. While I have preferably illustrated a bundle binding mechanism having a lead-off member consisting of two coadjacently mounted lead-off guide pulleys, it will be understood by those skilled in the art, that if one of said pulleys is removed, the wire may be so encircled about the other pulley as to provide for convexly tensioning the same to effect tight hugging of the bundle and the disposing of the wire within the knotter mechanism in each direction of movement of the member, and twice during each cycle of movement thereof; for example, the pulley 95, Fig. 2, may be removed and the wire 108, shown in said figure, trained to lead from the gripper over the pulley 94 and around said pulley upwardly to the pulley 96.

It will appear from the foregoing, that the bundle binding device, or mechanism, of this invention is a radical departure from the bundle binding devices of the prior art and I intend to claim the same, and the original features thereof, in the broadest scope.

The member 38 whatever its end construction mounts a pulley wheel 96 (Figs. 1 and 3) which conveniently is on the pivotal element connecting the outer end of link 37 with the member 38. A second pulley or wheel 97 is adjacent the pulley 96, the two being close together in a manner similar to the pulleys 94, 95 so that the wire leads off from one or the other according to the positions of the mechanism. When the parts are as shown in Fig. 3, the wire 108 leads off from the upper pulley 97, while when the member 38 is in the position of Fig. 2, the wire may be said to lead off from the lower pulley 96.

Referring to Figs. 2, 3 and 8, it is seen that the rear rod 39 supports a bar 102^a so that the bar may rock thereon in a vertical plane. On the bar 102^a is a pair of pulleys 98, 99 which turn on horizontally disposed pivots; these pulleys are spaced apart such a short distance that the wire 108 passes from one to the other just as it shifts between pulleys 96, 97 and pulleys 94, 95. From

the uppermost pulley 99 the wire passes about a pulley 100 disposed at right angles to the pulley 99 but also lying in a vertical plane, and then the wire passes about a pulley 101 disposed in a horizontal plane and at the upper end of bar 102^a. (See also Fig. 14). As will be evident from Figs. 2 and 3 the lead-off guide pulleys 94 and 95 mounted in respective wire guiding positions on the member 38, maintain the wire, extending from the pulleys 98 and 99 to the lead-off guide pulleys 94 and 95, clear of the bundle as the wire is fed to said lead-off guide pulleys during movement of the member 38 and said lead-off guide pulleys about the bundle.

15 The machine mounts an improved wire slack take-up device which also maintains a tension on the wire. Because of the oscillatory, or alternating directions of movement of the bundle binding means 94 and 95, it will be readily understood that the wire must be retracted and fed in tensioned state in order to provide the wrapping of a tensioned wire about a bundle and for such reason, the new and useful device herein shown has been devised to take up the slack automatically. Referring to Figs. 1, 2 and 14, but particularly to the latter, an arm 102 is there shown as pivoted near the top of the machine frame so as to swing in a horizontal plane. A coil spring 103 is connected at one end to an intermediate point of the arm 102 and at the other end is joined to a screw-threaded rod 104. This screw-threaded rod is received within a hollow stem 105. A nut joins the parts 104, 105 together whereby the tension of the spring 103 may be regulated at will. The stem 105 has an enlargement 106 which is slidable along one of the frame connecting rods 39. A set screw holds stem 105 fixed upon the rod 39. Obviously, by changing the position of the stem 105 and by moving the rod 104 in and out of the stem, the pull of the spring 103 on the swinging slack take-up arm 102 may be regulated as desired.

As Fig. 14 best shows, the swinging end of arm 102 carries three pulleys 110, 111, 112, the latter being set in a yoke piece or frame 113 having a set screw 114 which works against the arm 102 (Fig. 15) so as to adjust the position of the pulley 112 toward and from the other two pulleys. The pulley 112 may be termed a "crowding pulley" since it may be moved up into touching relation to the other two pulleys, whereby the feed of the wire is retarded as desired. The outer pulley 111 is provided with a spring-pressed friction disk 111^a to retard free rotation thereof. (Fig. 15^a). The combination of the three pulleys one of which is adjustable toward the other two, and the outer of which is restrained from free turning, constitutes a wire tensioning means which is active only when the wire is fed or paid out. The swinging arm 102 on the contrary is active at all times to take up automatically any slack formed in the wire. The supply of wire is conveniently carried upon a reel supported by a bracket 107, in turn secured to a transverse horizontal bar 109 mounted upon the rods 39. As the wrapping means moves toward and from the pulleys 98 and 99, the wire tensioning and slack take-up device retracts the wire in tension by oscillating between the full line and dotted line positions of Fig. 14, or even beyond the dotted line position. This action may be modified to suit the particular requirements. The wire tensioner and slack take-up device herein disclosed is an improvement from the standpoint of adaptability over the corresponding mechanisms

described and claimed in my Patent No. 1,295,531, dated February 25, 1919, inasmuch as it co-operates with the wire laying means to both yield and retract a considerable length of wire in accordance with bundle binding considerations.

Although I have shown a certain type of co-operating wire tensioning and slack take-up means it is my intention to claim and use any equivalent means for tensioningly retracting the wire during the operation of wrapping means movable in alternate directions a distance sufficient to permit the binding of bundles without recourse to movement of the bundles during the binding thereof.

The knotting mechanism, the driving means therefor and associated machine parts will now be described. As seen in Fig. 1, the countershaft 24 extends longitudinally of the machine and mounts at one end a gear 23, this gear having a flat 25 (Fig. 3) adapted to ride over the periphery of the intermittent gear 21. The teeth of the gear 23 engage with the teeth 22 of the intermittent gear whereby the countershaft 24 is intermittently driven. At an intermediate point the countershaft 24 mounts a bevel gear 115 meshing with a bevel pinion 115^a, fast to a knoter drive shaft 117 rotatable in a housing 118. The lower end of the housing is bifurcated as indicated at 119, the bifurcations straddling the countershaft 24 where the bevel gear 115 is fixed. The upper end of the housing 118 is joined to or made integral with a knoter mechanism housing 120. The latter is fast between a pair of intermediate bundle supports 121 corresponding to the outer end supports 55 (see Figs. 1 and 3). In place of two intermediate bundle supports a single casting may be provided appropriately fashioned to receive the knoter mechanism. The supports 121 are designated intermediate supports only for the purpose of description, for in fact they are primary and stationary supports providing means for supporting bundles of themselves and independently of the adjustable supports 55. If desired, conveyer chains 122 may run in guides provided on the intermediate bundle support or supports, and these chains will have bundle engaging lugs 123 similar to (Fig. 3) lugs 74. The shaft 73 may be employed to actuate chains 122 simultaneously with the chains 64. It is not necessary to provide these intermediate conveyer chains but they are useful if the bundles to be bound are of considerable length.

Near the upper end of the shaft 117 a knoter drive gear 124 is secured so as to rotate in a horizontal plane. (See Figs. 9 to 13, inclusive.) Also secured to the shaft 117 is a disk 125 preferably adjacent the gear 124 but beneath the same. Projecting from the disk is a gripper and cutter 126 having a beveled face and a knife edge 127, the knife edge being straight and adjacent the upper side of the cutter. As seen in Figs. 10 and 11, the gripper and cutter element 127 is beveled from the knife edge to the lower edge thereof to bend and grip the wire against the cooperating gripping element 129. A bracket 128 is fixed upon and projects from the forward side of the knoter mechanism housing and support. The wire gripping element 129 is pivoted upon housing 120 so as to swing in a vertical plane forwardly of the housing 120. A bolt 130 is connected to the swingable gripping member 129 and passes through a perforation provided in bracket 128. A nut 131 secured to bolt 130 on the under side of bracket 128 provides means

whereby the tension of the spring 133 surrounding the bolt 130 may be adjusted. The action of the spring 133 is to press the gripping element 129 tightly against the wire for firmly holding the same under predetermined spring pressure and to compensate the movement of the gripping member for gripping different thicknesses of wire. In machines of this type it will be understood that the severe tension put on the wire tends to elongate the wire and thereby cause variation in the size thereof and in order to provide a gripping member suitable for positive gripping of the wire, irrespective of such variations in the wire, I have devised the new and useful adjustable spring pressed gripping member, or gripper, disclosed in Fig. 9. When the cutter and gripper 126 rotates to sever and grip the wire, the lower edge of said cutter and gripper kinks or bends the portion of the wire to be gripped over the gripper, simultaneously with the severing thereof, so that the wire is securely held by the cutter and gripping mechanism 126 and the cooperating gripping member 129 when the tie strand is severed from the wire extending beyond the gripper. The gripper has a groove 132 into which the bent end of the wire 108 is adapted to be received immediately after it has been severed by the knife edge 121 and which groove, or depression, may be of any desired depth or width, which serves the purpose of preventing the escape of the gripped end when the binding means moves in a direction tending to pull the tensioned wire sidewise from its gripping position. A bracket 135 is formed integrally with the housing 120 but projects beyond the same to support and substantially enclose a knotter head 137. This knotter head has a gear 134 secured thereto and meshing with and driven by the gear 124, the knotter head being therefore rotatable with the supporting bracket 135. The lower face of gear 134 comes flush with the cutter 126 to form a shearing edge. The bracket 135 is slotted as indicated at 136, this slot being V shaped or tapering in width inwardly. The depth of this slot is sufficient to bring the wire 108 to the exact center of the knotter head, if desired, so that one end of the wire may be coiled about the other. If, however, a twist knot is to be made, this slot will extend not quite to or beyond the center whereupon the wire ends will be twisted about each other. The drawings (Figs. 9 and 10) indicate a twist knot 138 with the extremities of the tie strands in the same parallel relation as originally provided by the banding means. The knotter head itself is slotted differentially as indicated at 139, Fig. 12. This slot is co-extensive in depth with the slot 136, and is narrow at the bottom of the gear 134 but widens out about a quarter of an inch from the bottom so that the knot whether a twist or a coil can be formed in the widened portion of the slot of the gear; said portion being of sufficient width to permit discharge of the completed knot, through the knotter, towards the bundle. As seen in Fig. 12, the slot 139 flares outwardly for a portion of its depth so as to guide the wire 108 into the knotter head and has substantially parallel walls for the remainder of its depth.

Although I have shown a certain type of knotter mechanism the generic principles of my invention provide for the use of any equivalent device adapted to receive successive tie strands during each binding operation directly from the wrapping means in parallel relation therein, and

to unite said strands to secure a band about a bundle.

The general operation of the machine will now be described. It is presumed that necessary adjustments for length, width and height of the bundle or box have been made. The machine comes to rest after one of its cycles of operation in the position indicated in Fig. 2, with the end of the lead of the wire 108 extending from the lead-off guide pulley 95 below the plane of the support 5 gripped by the gripper 129. The bundle is placed on the support and manually located in binding and tying position against the abutment bars and above the knotter mechanism. If the bundle consists of shocks, or a number of articles, the same will be abutted against these bars whereby the shocks, or articles, will be aligned for binding, but if a box, or object of definite dimensions is being bound, it need only be located against the abutment bars. When the bundle is so located, it rests above and distant from the lead section of the wire 108 disposed in the passageway provided therefor between the stationary bundle supporting elements 121, as shown in Figs. 1, 2 and 4. First the foot lever 18 is tripped, throwing the clutch 16 into engagement with the main shaft 20 and the cycle of operation of the machine starts, the machine having one cycle of operation for the binding of each bundle. In the initial period of said cycle 30 of operation, the cams 42 on the shaft 20 cause actuation of the bundle clamping bars 61 to clamp the bundle, as is clearly evident from the showing of Figs. 2 and 2a. Simultaneously with the clamping of the bundle, the counterbalanced 35 latching bars 82 are depressed so that the abutment bars are released. The gravity trips 87 now hold the latching bars in depressed position. During the actuation of the clamping bars and while the bundle is held stationary by said bars 40 in the position in which it is manually placed, the member 38 and lead-off guide pulleys 94 and 95 move in the arcuate path shown in Fig. 16, from the initial position shown in Fig. 2 to the intermediate position of Fig. 3. The wire, the 45 end of which has been previously secured by the gripper 129, now encloses four sides of the bundle and is laid in the slot of the twister 134 and extended therebeyond to a position at which the gripping of a new lead thereof for the subsequent binding operation may take place. The wire is wrapped into band formation about the successive faces of the stationary bundle from its position below the plane of the bundle support, as shown in Fig. 2, to the position below the 50 plane of the bundle support, shown in Fig. 3, during movement of the member 38 and lead-off guide pulleys 94 and 95 in their arcuate path of travel between the full line and broken line positions shown in Fig. 16. The intermittent 55 gear 21 next engages the gear 23 to cause rotation of the knotter mechanism drive shaft 117 for effecting actuation of the twister 134. As soon as the knot is well started and binding security is assured, the continued movement of the cams 60 42 releases the bundle clamping mechanism, but the latching means for the abutment bars are still maintained in their lower position by reason of the engagement of the gravity trips 87. At the completion of the knot, see Fig. 9, the cutter or knife 126, as it revolves, severs the wire extending between the tie and the pulley 94 and at the same instant bends the free cut-off end over the spring actuated gripping element 129, and the end of the wire is laid in the groove 132, being held by the 65 70 75

pressure of the spring 133. This cutting and gripping of the wire provides a newly gripped lead of the wire extending from the gripper 129 to the pulley 94. Immediately after the wire is severed and the free end is secured, the bundle conveyor is put into motion and the lugs 14, 123 engage the lower portion of the tied bundle and move the same out of the machine. This movement of the bundle pulls the knot 138 out of the slot of the knotter head. The bundle swings the abutment bars 78 upwardly and also engages the gravity trips 87. While the bound bundle is being moved to release the knot from the twister and out of the machine, the cam groove 26 actuates the member 38 to return the same to the initial position of Fig. 2, and the newly gripped end of the wire changes its position from that shown in Figs. 9, 10 and 11 to the position shown in said Fig. 2; to provide for more ready and quick application of the wire about a succeeding bundle to be bound in the next cycle of operation of the machine. In the construction of Figs. 2 and 3, it will be seen that the primary actuating elements 21 and 42, mounted on the drive shaft 20, are designed to provide simultaneous actuation of the clamping means and the bundle binding mechanism during the initial period of a cycle of operation of the machine and actuation of the bundle moving means simultaneously with the return of the bundle binding mechanism to the initial position of Fig. 2, during the final period of such cycle of operation. It will be understood that in reversing and moving the member 38 and lead-off guide pulleys 94 and 95, or 94 and 95a, with the newly gripped lead of the wire to the initial position of Fig. 2 simultaneously with the removal of the bound bundle from the twister, or out of the machine, my invention makes for lesser movement of said member and lead-off guide pulleys and more ready and quick application of the wire about a succeeding bundle to be bound in the next cycle of operation of the machine, than if said member and lead-off guide pulleys remained at rest in the position at which the binding of the bundle is completed. As soon as the bundle is clear of the machine, the abutment bars 78 swing downwardly to their initial position and the latch pieces 83 lock therewith to hold the same in upright position.

Fig. 17 illustrates a machine adapted to place two wires simultaneously about a bundle and tie the same. Inasmuch as this machine is almost identical in construction with the previously described machine, only those parts will be touched upon which represent differences. Here the main drive shaft 20 mounts two of the intermittent gears 21, one at each end. The trip portion 17 of the clutch passes through a bracket 140 mounted on the frame. There are two intermediate bundle supports 121 each carrying a knotter mechanism. Screw-threaded adjusting rods 141 are connected with the shaft housings 118 in any desirable way, whereby turning of the shafts 141 adjusts the positions of the intermediate bundle supports. The bundle end supports 55 are independently adjustable by means of screw-threaded rods 142. There are two members 38 which are carried by the auxiliary frames 41, and these auxiliary frames are adjustable independently of the remainder of the mechanisms by means of the screw-threaded shafts 143 engaged with the main machine frame. The means for actuating the members 38 are duplicated on each side of the machine. The bracket 146 holds the gear 34 in mesh with the quadrant gear 33 and a

single longitudinally extending shaft 144 having a keyway 145 at each end provides means whereby the reversing or oscillation of the two members 38 takes place simultaneously. It is necessary that the adjustment of each member 38 correspond exactly with the adjustment of the intermediate bundle supports 121 in order that the wire may be laid into the slot in the knotter head as previously described. A machine of this character is not only capable of handling bundles of any length, height and width, but may place two or more bands about such bundles at the desired points. The wire tensioning and slack take-up means described in connection with the machine having the single member 38 may be used with the machine of Fig. 17, if desired. For simplicity they are omitted from that figure.

Fig. 18 is an incomplete view of still another machine embodying the principles of the present invention and designed to handle two bundles, which may be of different dimensions, simultaneously. With this machine, each bundle has a wire or band placed about it either at the middle or at any other desired point. This machine employs the construction of the previously described machine, but the arrangement is somewhat different. If Fig. 18 is compared with Fig. 17, it will be found that an intermediate bundle support 150 has been provided, which bundle support has associated therewith two bundle clamping means. This intermediate bundle support 150 is adapted to uphold the ends of two bundles which are in alignment longitudinally of the machine. Two bundle alining means are also provided on this intermediate bundle support as well as two bundle conveying means. The clamping bars 61a of the two bundle clamping means may be made independently adjustable so that while both are depressed by the same cam 42, two bundles of varying heights can be handled at the same time by the single machine. The abutment bars 78 are of course independently adjustable; hence two bundles of different widths might also be bound and tied at the same time. The figure illustrates two bundles 63a, 63b, upon the machine, of which the bundle 63b is the longer. Obviously, by merely duplicating the bundle supports 150 and the associated mechanisms, it is possible to construct machines capable of binding and tying any number of different sized bundles simultaneously.

Machines of the present application have features in common with the machine of Patent No. 1,295,531, reissued May 24, 1921, No. 15,111. The present machines also have features in common with two co-pending applications Serial Nos. 380,375 and 380,376, filed May 10, 1920. In the specification and claims, I have employed certain words and terms, the scope and meaning of which I hereinafter set forth.

When I use the word "oscillatory", or terms indicating an oscillatory motion, I have reference to the alternating clockwise and counter-clockwise movements of the binding means in a curvilinear path.

When I use the words "around" and "about" relative to the movement of the binding means, I have reference to the movement of the binding means a sufficient distance in a curvilinear path to wrap a wire into band formation about a bundle with portions of the wire band overlapped in the plane in which the wire was wrapped.

When I use the words "within the path of travel", or "within the path of movement", with reference to the bundle binding mechanism, I have reference to the movement of said mecha-

nism as the same moves in its arcuate or curvilinear path about an imaginary axis above the bundle support.

When I use the words, "tying, knotting, uniting" etc., I have reference to intertwisting, coiling, interlocking, or uniting of the wire in any manner to secure a band about a bundle.

When I use the term "lead of the wire", I have reference to that advance portion of wire 10 initially guided into position below the plane of the support for the purpose of beginning the banding of the bundle about the lower face thereof and providing the initial tie strand of the wire which is overlapped when the wire is 15 wrapped into band formation about the bundle.

When I use the term "fed portion of the wire", I have reference to that section of the wire delivered by the slack takeup and tensioning means 20 and extending from said means to the gripping means.

When I use the words or terms "convexed", "convexly tensioned" or "convexed tensioning", or words to such effect with respect to the wire, I have reference to the manner in which the wire 25 is processed or tensioned to press or convex inwardly against the sides of the bundle, so as to tightly hug and lie substantially flat against the periphery thereof.

When I use the term "adjustably clamping", I 30 have reference to the action of the bundle clamp in automatically accommodating itself to clamp bundles of different dimensions within the range of compressibility of the yieldable means which compensate the action of said clamp.

If boxes are handled it is frequently desired to 35 place flat bands about the same. The machines of the present invention are readily adapted to do such work by eliminating the knotter mechanism or by merely disconnecting the same, and by 40 changing the shapes of the pulleys so that they are adapted to guide flat bands instead of round wire, whereupon such bands may be placed about the boxes and secured in place by staples. When this work is done, a staple will first secure the 45 free end of the band to the box at a low point thereon; then after the box has been wrapped, a second staple will be used to hold the other end of the band to the box. The machine may be stopped if desired at this point. The pulleys of 50 the tension device may be slightly modified for flat band in accordance with the construction disclosed in application Serial No. 380,376.

In view of the foregoing description of my machine it will be readily seen that the wire binding device 38 (Figs. 9 and 16), has an oscillatory motion in an arcuate path of travel about a stationary bundle; that it draws out and wraps a wire progressively about the successive faces of the bundle and positions tie strands of the wire 55 (Figs. 9 and 10) within the knotting mechanism without the aid of auxiliary devices; and while I herein show a certain type of binding mechanism for producing this bundle encircling movement, I feel entitled to claim any type of encircling device which is reversible relative to the knotter mechanism to provide for the binding of bundles in the manner as aforesaid.

Obviously the present invention is not restricted to the particular embodiments thereof herein shown and described. Moreover, it is not indispensable that all the features of the invention be used conjointly since they may be employed advantageously in various combinations and subcombinations as defined in the claims.

What I claim is:

1. In a machine of the class described, a fixed bundle support; band gripping means below the support; means for operating the band gripping means to grip the band; means for guiding the band from the position at which it is gripped to another position below the plane of the support preparatory to the binding of a bundle, and means for moving the band guiding means whereby the band is wrapped entirely around a bundle placed 10 on the support.

2. A machine of the class described, comprising, in combination, an oscillatory member for wrapping a wire about a bundle; spaced wire-guiding wheels on said member for leading the 15 supply wire; wire tying means including a rotary slotted twister disposed in the path of movement of the wire; some of the wire guiding wheels holding the supply wire spaced from all parts of the bundle and two of the guiding wheels arranged 20 for guiding the wire into band formation about the bundle, and disposing within the slot of the twister each bight of the wire required to form the tie for securing the band about the bundle; means to actuate the tying means; and means for oscillating the member comprising a rack and pinion, a drive shaft, a rotary element mounted on said drive shaft, and connections between the rack and said rotary element for reciprocating the rack to oscillate the pinion and binding member. 25

3. In a machine of the class described, band gripping means; means for operating the band gripping means to grip the band; means for guiding the band from the position at which it is gripped to a position below the plane of advancing a bundle into binding location; means for supporting the bundle whereby the bundle stands over the band and rests in said location; means for actuating the guiding means whereby the 35 band encloses the stationary bundle, and means operative to engage and press the bundle against the support during the movement of the guiding means.

4. In a machine of the class described, band 45 gripping means; means for operating the band gripping means to grip the band; means for guiding the band from the position at which it is gripped to a position below the plane of advancing a bundle into binding location; means for 50 supporting the bundle whereby the bundle stands over the band and rests in said location; means for actuating the guiding means whereby the band encloses the stationary bundle; means operative to engage and press the bundle against 55 its support during movement of the guiding means; means for tying the band; means for cutting the tied band free from the band; and means for moving the tied bundle out of tying location.

5. In a machine of the class described, a bundle support, bundle abutment means mounted to swing above the support, and means for maintaining the abutment means normally in a position at right angles to the support, said means returning the abutment to its normal position 60 after displacement.

6. In a machine of the class described, a bundle support, bundle abutment means mounted to swing above the support, and means on the support for automatically latching the abutment 65 means when in a position perpendicular to the support.

7. In a machine of the class described, a bundle support, bundle abutment means swingable relative to the support, and locking means mounted 75

on the support for holding the abutment means in bundle aligning position.

8. In a machine of the class described, a bundle support, a frame secured rigidly upon and rising above the support, a bundle aligning abutment bar pivoted at its upper end upon the frame, means for causing said bar to swing into a vertical position, bar locking means mounted on the bundle support, and means causing said locking means to move into a position where it catches and holds the bar as the latter assumes a vertical position.

9. In a machine of the class described comprising in combination, a frame; a bundle support stationary relative to the frame; means below the support for gripping a band; means against which to manually place a bundle located upon the support; means for tying the band; means for passing the band about the located bundle; means for tying the band passed about the bundle; means for cutting the tied portion of the band from the band; means for reversing the direction of movement of the band passing means, the reversal of direction of said means serving to return the band to a position below the support; and means to engage and move the tied bundle out of the machine after the tying is completed.

10. In a machine of the class described comprising in combination, a frame; a bundle support stationary relative to the frame; means adjustable relative to the support against which to place a bundle directly in tying location upon the support; means for gripping the end of a band; oscillatory means for binding the band about the located bundle; means for securing the band about the bundle; bundle moving means; and means for operating the bundle moving means to engage and move the bound bundles out of tying location.

11. In a machine of the class described, comprising in combination, means for gripping the end of a lead of a band; means fixedly positioned for supporting a bundle; means adjustable relative to the supporting means against which the bundle is manually located in binding position and rests above the lead of the band; means for passing the band in one direction about the stationary bundle; means for receiving and uniting overlapping portions of the band encircled about the bundle; means for severing the united portions of the band from the band; means for moving the bundle out of said tying location; and means for reversing the direction of movement of the band passing means to return said means to an initial position with the band positioned below the support.

12. In a machine for binding bundles with a wire, a frame; bundle supports and abutments positioned to provide a passageway for movement of the wire and to receive a bundle directly into tying location; a clamp movable relative to the support for holding the bundle so located; a device for holding the end of the wire; a device operative on the wire for delivering the wire under tension and for preventing slack in the wire; a carrier member having spaced wire guiding means mounted thereon in respective band guiding positions whereby during movement of said member in a vertical plane extending into said passageway the lead of the wire is alternately guided by said spaced means for convexly tensioning and binding the wire about the bundle; a device for tying the wire band; a device for severing the wire beyond the tie; means for actuating the carrier; means for actuating the clamp

simultaneously with the initial movement of the carrier; means for actuating the tying device; and means for moving the bundle relative to the support to release the formed tie from within the tying device.

13. In a machine of the class described, oscillatory means for wrapping a band progressively about the successive faces of a bundle without recourse to movement of the bundle; means for tying the band; means for moving the tied bundle out of the machine; and a single power-actuated element for actuating all three of the specified means.

14. In a machine of the class described, a support; an abutment adjustable relative to the support against which to locate a bundle directly in tying position on the support; means for guiding a band about the bundle; means for tying the band; means for moving the tied bundle away from the tying means to release the tie, a combination rotary gear and cam power-actuated element, mechanism intermittently driven by the element for actuating the band guiding means, mechanism intermittently driven by the element for actuating the tying means, and mechanism intermittently driven by the element for actuating the moving means.

15. In a machine of the class described, bundle registering and bundle supporting means arranged to receive and register a bundle directly into binding position prior to any binding thereof; means for binding the bundle with a wire band and means for tying the band about the located bundle; means for moving the bound bundle out of the machine comprising elements movable from below the plane of the support for engaging the lower part of the bundle; mechanism becoming active only after the tying of the bundle has been completed for driving said elements, said mechanism including a power-driven intermittent gear and a pinion for intermittently meshing with the teeth thereof.

16. In a machine of the class described, means for directly receiving and supporting a bundle in tying location; means for clamping the bundle so located; oscillatory means for wrapping a band about the located bundle; means for actuating the wrapping means; means for actuating the clamping means simultaneously with the initial movement of the wrapping means; means for automatically maintaining the band in tension and preventing slack in the band during the wrapping operation; means for tying the band; and means for moving the tied bundle horizontally out of said tying location.

17. A machine of the class described, comprising in combination, a support for a bundle; means for gripping the end of a band; tying means and cutting means; for the band cooperating with the gripping means; a carrier element; band guiding means mounted on said element with the lead of the band initially below the plane of the support and movable in a curvilinear path toward and from the gripping means to arrange tie portions of the band in tying position within the tying means; means for actuating the carrier and the gripping means and the tying means and cutting means in their respective order to complete the banding of a bundle; means for removing the bundle for releasing the tie from within the tying means; the means for actuating the carrier reversing the direction of movement of the carrier at the end of its bundle banding movement and returning the band guiding means

to the initial position preparatory to the succeeding banding operation.

18. In a machine of the class described, a bundle support; an abutment adjustable relative to the support against which the bundle is directly placed in tying location; means for gripping the free end of a band; means mounted to reverse in an arcuate path and progressively to guide the lead of a band below the plane of the support in one direction of movement and to enclose a bundle located on the support with the band in the opposite direction of movement; means for tying the band; and means for severing the band.

19. A bundle tying machine, comprising, in combination, a frame; wire guiding means on the frame; spaced fixed bundle supporting elements; means for gripping the end of the wire; wire tying means; means on the frame for delivering the wire in tensioned state to the wire guiding means; a bundle binding mechanism reversible relative to the guiding means for convexly tensioning and wrapping the tensioned wire received therefrom into band formation about the supported bundle and for disposing each tie portion of the wire into the tying means; means comprising a rack and pinion for actuating and reversing the binding mechanism; and means for actuating the tying means for the intertwisting of the wire therein; said wire wrapping means moving in a plane extending between said bundle supports in one direction to encircle the supported bundle with the wire and in an opposite direction to position the wire below the plane of the support preparatory to the next bundle encircling movement during each cycle of movement thereof.

20. In a machine for binding a bundle with a wire; a frame; spaced bundle supports and abutments positioned to receive a bundle directly into tying location; a device for holding one end of the wire; a device for tensioning the wire; a device on the frame for taking up slack in the wire; a carrier reversible relative to the wire holding device in a vertical plane extending between said supports and having spaced wire guiding means mounted thereon in respective wire guiding positions whereby during movement of said carrier the lead of the wire transfers from one guiding means to the other to effect the binding of a bundle; driving means for actuating and reversing the carrier comprising a sector gear and pinion, a drive shaft, a rotary element mounted on the drive shaft, and a reversing bar connecting the sector gear and the rotary element; a device for tying the band; and a device for severing the wire beyond the tie.

21. A bundle tying machine comprising in combination, a bundle support; a wire tying mechanism; a device having an oscillatory motion in a vertical plane toward and from said tying mechanism for disposing the wire therein, said device wrapping the wire in said plane first into the tying mechanism, then about a bundle positioned on the support and again into the tying mechanism to overlap the wire therein; means for gripping the wire extending beyond the tying mechanism at the end of its movement around the bundle; means for actuating the tying mechanism to intertwist the overlapped portions; means to cut the tied portions of the wire from the wire between the twister and the gripping means; and means for oscillating the device through a cycle comprising one direction of movement of the device to effect the binding of the bundle and a reverse direction of movement to

return the lead of the wire to its initial position below the support.

22. A bundle tying machine comprising, in combination, a bundle support; a wire tying mechanism including a slotted rotary twister; a device having an oscillatory motion in a vertical plane toward and from said tying mechanism for disposing the wire within the slot of the twister; said device wrapping the wire in said plane first into the slot of the twister, then about a bundle positioned on the support and again into said slot to overlap the wire therein for intertwisting therein; means for gripping the wire extending beyond the twister at the end of its movement around the bundle; means for actuating the tying mechanism to effect intertwisting of the overlapped wire; means to cut the tied overlapped wire from the wire between the twister and the gripping means; means for oscillating the device through a cycle comprising one direction of movement of the device to effect the binding of the bundle and a reverse direction of movement to return the lead of the wire to its initial position below the support; and means for preventing slack in the wire during the oscillation of said device.

23. In a bundle tying machine, a bundle support; wire tying means; a bundle binding device mounted so as to oscillate in a plane at right angles to the plane of the bundle support, said device moving in one direction for arranging the lead of a band in position for quick application about a horizontal face of a bundle and enclosing a supported bundle with said lead section and the band in its alternate direction of movement; means for oscillating said device comprising a sector gear and pinion, a drive shaft, a rotary element mounted on the drive shaft, and a reversing bar connecting the sector gear and the rotary element for oscillating the sector gear.

24. A machine of the class described comprising, in combination, means for securely holding one end of a band; means to support a bundle; a reversible wire guiding mechanism operable alternately in opposite directions to arrange, by movement in one direction, the lead of the band below the plane of the support, preparatory to the binding of the bundle, and to enclose the periphery of the bundle with the band during movement in the opposite direction; means for actuating and reversing the guide mechanism comprising a sector gear and pinion, a drive shaft, a rotary element mounted on the drive shaft, and a reversing bar connecting the sector and the rotary element.

25. A machine of the class described comprising, in combination, a frame; means on the frame for maintaining a band under adjustable tension; a bundle support; a carrier mounted to move alternately in clockwise and counter-clockwise directions relative to said support; band guiding wheels mounted on said carrier for guiding the lead of a band below the plane of the support and thereafter applying said lead and the band about a bundle positioned on the support; and means on the frame for guiding the tensioned band to the band guiding wheels of said carrier; means for actuating and reversing the guide mechanism comprising a sector gear and pinion, a drive shaft, a rotary element mounted on the drive shaft, and a reversing bar connecting the sector gear and said rotary element.

26. A machine of the class described, comprising in combination, means for supporting a bundle; means adjustable relative to said sup-

port for locating the bundle directly into tying position upon the support; means below the support for holding the end of a wire; a carrier element; wire guiding means mounted on said element for convexing and binding the wire about the stationary bundle; and means for operating the carrier alternately in opposite directions whereby the guiding means moves away from and back to the gripping means for completely enclosing the bundle with the wire.

27. A bundle tying machine comprising, in combination, a bundle support; means for clamping a bundle on the support; a device for tensioning a wire; a wire tying mechanism; a device having an oscillatory motion toward and from said tying mechanism for wrapping the wire therein; said device wrapping the wire first into the tying mechanism, then about a bundle positioned on the support and again into the tying mechanism to overlap the wire therein for intertwisting to complete the banding and tying of the bundle; means for actuating the tying mechanism; means to cut the tied band free from the wire leading to the device; and means for ejecting the bound bundle out of the machine.

28. A bundle tying machine comprising, in combination, means for holding the end of a wire; a bundle support; wire tying means; an abutment against which to position a bundle in tying location upon the support; a clamp movable toward the bundle for adjustably engaging and holding the bundle so located for banding; a device having an oscillatory movement toward and from the tying means for passing the wire into said tying means, then about a bundle positioned on the support and again into said means for intertwisting therein to complete the banding of the bundle; means for oscillating said device; means for actuating the clamp to clamp the bundle during the initial movement of said device; means for actuating the tying means; means for severing the wire beyond the tie; and means for moving the bound bundle and releasing the tie from within the tying means; said device oscillating in one direction during the banding of the bundle and in the opposite direction during the movement of the bundle away from the tying means.

29. A machine of the class described comprising, in combination, wire tying means; a device reversible relative to the tying means and having means rotative against a wire for convexly tensioning and wrapping the wire around a bundle and disposing portions of the wire in overlapping tying position within the tying means; means for actuating the tying means to intertwistingly unite said portions to secure the wire wrapped around the bundle; a motor for driving the device; and reversing mechanism including a rack and a pinion, and a rotary element for actuating the rack, interposed between the motor and the device for operating the device alternately in opposite directions.

30. A machine of the class described comprising in combination, wire tying means; a device reversible relative to the tying means and having rotary wire guiding means mounted in a vertical plane on the side thereof between which the wire passes as said guiding means rotate against the wire for convexly tensioning and wrapping the wire around a bundle and disposing portions of the wire in overlapping tying position within the tying means; means for actuating the tying means to intertwistingly unite said portions to secure the wire wrapped around the bundle; a

motor for driving the device; and reversing mechanism including a rack and a pinion and a rotary element interposed between the motor and the element to diminish the speed of the element at its position of reversal and to accelerate the speed of the element after its reversal, thereby eliminating the shock of suddenly stopping or starting the device.

31. A machine of the character described comprising, in combination, a frame; means mounted on the frame for delivering wire under predetermined tension; a bundle support stationary relative to the frame; means for clamping a bundle in binding position on the support; mechanism for encircling the bundle with the wire while in binding position and for arranging tie portions of the wrapped wire in tying position; a rotatable slotted twister positioned in the path of the wire to receive within its slot said tie portions of the encircling wire to intertwist the same; a drive shaft supported on the frame; a rotary element mounted on the drive shaft for actuating the binding means and the twister in succession; a cam on the drive shaft for actuating the clamping means simultaneously with the initial actuation of the binding means; a motor for actuating the drive shaft; and a clutch to disconnect the drive shaft from the motor at the completion of the binding operation.

32. A machine of the class described comprising, in combination, an apparatus mounted and actuated so as to move in an arcuate path about two sides and the top of a bundle at one stroke, and in the return stroke to lay out a length of wire for the succeeding bundle; wire tying means positioned in the plane of movement of said wrapping means; and means for reversing the direction of movement of said apparatus at the end of each stroke.

33. In a bundle binding and tying machine, a tying mechanism; a bundle support; a bundle abutment adjustable relative to the tying mechanism; bundle clamping means including a guide bar; a clamping bar adjustably secured on the guide bar; a pivotally mounted arm connected to the guide bar; a rotatable shaft; means for driving the shaft; and a cam on said shaft for actuating the arm for actuating the clamping bar to clamp the bundle.

34. In a bundle binding and tying machine, a tying mechanism; a bundle support; a bundle abutment adjustable relative to the tying mechanism; bundle clamping means including a guide bar; a clamping bar adjustably secured to the guide bar; a pivotally mounted arm; a spring to compensate the movement of the clamping bar relative to the size of the bundle; a power driven shaft; and a cam on said shaft and engaging said arm, for actuating the clamping bar to clamp the bundle.

35. In a machine of the class described, a bundle support; a guide bar slidably mounted upon said support and movable at right angles thereto; a clamping bar secured to the guide bar; means interposed between the guide bar and the bundle support whereby the guide bar and the clamping bar are normally held above a bundle held upon the support; a power driven cam; an arm oscillated by said cam, said arm being connected with said guide bar whereby the cam acts to clamp the bundle.

36. In a machine of the class described, means for receiving and supporting a bundle; means for wrapping a band about the supported bundle; means for tying the band; clamping means for

5 putting pressure on the bundle during the operation of the bundle wrapping means; said clamping means including a cam for actuating the clamp to clamp the bundle and a spring for releasing the clamp from the bundle after the wire has been sufficiently tied to insure a tightly bound bundle.

10 37. In a machine of the class described, means for supporting a bundle; means for clamping the bundle on its support; means for wrapping a band about the bundle; means for tying the band; means for actuating the clamping means including a cam and a spring operable to alternately move the clamp in opposite directions for the 15 engagement of the bundle during the initial operation of the wrapping thereof and for releasing the bundle after the wrapped wire has been sufficiently tied to insure a tightly bound bundle and means for pushing the tied bundle out of 20 binding position.

25 38. A machine of the class described comprising, in combination, a bundle support; means positioned to receive a bundle directly into tying location on the support; tying mechanism, binding mechanism having gradually accelerating starting movement during the initial binding of the supported bundle; a motor for actuating said mechanism and means disposed between the motor and the mechanism comprising a rack and 30 pinion, a drive shaft, a rotary element mounted on the drive shaft, and a controlling bar connecting the rack and the rotary element for controlling the movement of said binding means during the entire operation thereof.

35 39. In a machine of the class described, a bundle support; means for conveying a bundle relative to the support; means for arranging the lead of a band in one direction of movement of said means to a position below the plane of the bundle support preparatory to the binding of the bundle; and means for moving the latter means in the opposite direction, whereby the band is wrapped completely about the bundle; said last named means comprising a rack and a pinion, 40 drive shaft, a rotary element mounted on the drive shaft, and an actuating and reversing bar connecting the rack and the rotary element.

45 40. A machine of the class described comprising, in combination, a support for a bundle; a carrier element; band guiding means mounted on the element and movable over the bundle in one direction from one position below the support to another position below the support for convexing and binding a band about the bundle; means for tying the band; means for gripping the band beyond the tying means; means for cutting the band between the tie and the gripped end; means for moving the bundle to release the tie from within the tying means; and means for 50 actuating the carrier in an opposite direction for guiding the band into the tying means preparatory to the succeeding banding operation.

55 41. A machine of the class described comprising, in combination, a support for a bundle; a carrier element; band guiding means mounted on the element and movable over the bundle in one direction from one position below the support to another position below the support for convexing and binding a band about the bundle; means for clamping the bundle on the support during movement of the guiding means; means for tying the band; means for gripping the band beyond the tying means; means for severing the tie from the gripped band; means for 60 moving the bundle to release the tie from within 65

the tying means; and means for actuating the carrier in an opposite direction for guiding the band into the tying means preparatory to the succeeding banding operation.

70 42. In a machine of the class described, a frame, a plurality of bundle supporting and bundle clamping means adjustable toward and from each other on the frame to accommodate bundles of different lengths, bundle binding and bundle tying means intermediate the bundle supports and fixed relative to the frame and operable to effect the binding of a bundle irrespective of the adjustment of the supporting means.

75 43. A machine of the class described comprising in combination, a frame, a plurality of bundle supporting and bundle clamping means adjustable toward and from each other on the frame to accommodate bundles of different lengths, bundle binding and bundle tying means intermediate the bundle supports and fixed relative to the frame and operable to effect the binding of a bundle irrespective of the adjustment of the supporting means, and a plurality of means for pushing the bundle off its supports, each pushing means cooperating with one of the bundle supporting means whereby the moving means and bundle supporting means are adjustable together.

80 44. In a machine of the class described, a frame, a plurality of bundle supporting means adjustable toward and from each other on the frame to accommodate bundles of different lengths, abutment means associated with each supporting means whereby a bundle placed on the support may be thrust thereagainst for proper positioning and alignment, bundle binding and bundle tying means intermediate the bundle supports and fixed relative to the frame, said latter means being operable to effect the binding of a bundle irrespective of the adjustment of the first 85 named means.

85 45. A machine of the class described comprising, in combination, a frame, a plurality of bundle supporting means adjustable toward and from each other on the frame to accommodate bundles of different lengths, abutment means cooperating with each supporting means whereby a bundle placed on the support may be thrust thereagainst into proper positioning and alignment, bundle binding and bundle tying means 90 intermediate the bundle supports and fixed relative to the frame, said latter means being operable to effect the binding of a bundle irrespective of the adjustment of the first named means, and bundle moving means cooperating with each 95 supporting and abutment means and adjustable therewith, said moving means progressing the bound bundles out of the machine.

100 46. In a machine of the class described, a frame, a plurality of bundle supporting means adjustable toward and from each other on the frame to accommodate bundles of different lengths, bundle binding and bundle tying means intermediate the bundle supports and fixed relative to the frame and operable to effect the binding of a bundle irrespective of the adjustment of the supporting means, and an intermediate stationary bundle support, said tying means being mounted on the latter named support.

105 47. In a machine of the class described, a frame, a plurality of bundle supporting means adjustable toward and from each other on the frame to accommodate bundles of different lengths, bundle binding and bundle tying means 70 75

- intermediate the bundle supports and fixed relative to the frame and operable to effect the binding of a bundle irrespective of the adjustment of the supporting means, an intermediate 5 stationary bundle support, said tying means being mounted on the latter named support, and means mounted on each bundle supporting means and engageable with the bundle to move the same out of the machine after it has been bound.
10. 43. In a machine of the class described, a frame, a plurality of bundle supporting means adjustable toward and from each other on the frame to accommodate bundles of different lengths, bundle clamping means cooperating with 15 each bundle support and adjustable therewith, bundle binding and bundle tying means intermediate the bundle supports and fixed relative to the frame, said binding and tying means being operable to effect the binding of a bundle 20 irrespective of the adjustment of the supporting means, said clamping means holding the bundle during the binding operation and releasing the bundle after the tying begins.
25. 49. In a machine of the class described, means for supporting a bundle; means for positioning the bundle on its support; means for clamping the bundle, said means being relatively adjustable for various sizes of bundles; means for binding and means for tying bundles; and means 30 for conveying the tied bundles out of the machine, said latter means being adjustable along with the bundle supports.
35. 50. In a machine of the class described, a pair of bundle supports each adjustable for different lengths of bundles toward and from the medial plane of the machine; wire wrapping mechanism mounted to move substantially in said plane about a bundle carried by said supports from a position adjacent a lower edge of the bundle 40 to a position below the plane of the bundle support and back again to its initial position; and actuating means for said mechanism.
45. 51. In a machine of the class described, a wire binding and tying mechanism operative to wrap a wire band transversely about a bundle at the middle thereof whatever the dimensions of the bundle without recourse to movement of the bundle during the wrapping thereof and a pair of cooperating bundle supports adjustable toward and from the binding and tying mechanism whereby bundles of different lengths are 50 accommodated.
55. 52. A machine of the class described, comprising in combination, a pair of relatively adjustable bundle supports; a three-sided frame secured to and rising above each support, each frame including two uprights and a joining member parallel to the support, the frames and supports providing a variable bundle binding and 60 tying chamber.
65. 53. A machine of the class described comprising, in combination, a bundle support; wire tying means; wire guiding means mounted to oscillate in an arcuate path more than 180 degrees relative to said tying means whereby a bundle placed on the support is completely enclosed by wire with the overlapped wire in the tying means in each cycle of movement of said wire guiding means; means to actuate the tying means to intertwist the overlapped portions of the wire; and means for oscillating the latter means comprising a rack and pinion, a drive shaft, a rotary element mounted on the drive shaft, and an actuating 70 and reversing bar connecting the rack and

the rotary element for effecting oscillation of the guiding means.

54. A machine for tying a bundle comprising, in combination, a frame; means on the frame positioned to receive a bundle directly into tying 5 location; means for gripping the end of the wire; means on the frame for tensioning the wire; wire tying means; and a binding mechanism reversible relative to the support for convexing and wrapping the tensioned wire about the bundle so 10 located and for disposing each tie portion of the wire band in overlapping relation within the tying means, said wire wrapping mechanism moving more than 180 degrees in one direction for binding the bundle and having a like distance of 15 movement in an opposite direction to position the wire preparatory to banding the succeeding bundle; and means for actuating the binding mechanism comprising a sector gear and pinion, a drive shaft, a rotary element mounted on the 20 drive shaft, and an actuating and reversing bar connecting the sector gear and the rotary element.

55. A machine for tying bundles comprising, in combination, a frame; wire guiding means on 25 the frame; a device for gripping the end of a wire leading therefrom; an abutment adjustable relative to the support for locating the bundle in binding and tying position thereon; a wire twisting mechanism adjacent the gripping means; a 30 device operable on the strand of wire intermediate the gripping device and the guiding means for passing an initial tie portion of the wire to be banded about a bundle into the twisting mechanism preliminary to the binding thereof and 35 for wrapping the wire a sufficient distance about a positioned bundle to completely enclose the same and overlap the tie portion within the twisting mechanism for intertwisting therein; and means for oscillating said device comprising a 40 sector gear and pinion, a drive shaft, a rotary element mounted on the drive shaft, and an actuating and reversing bar connecting the sector gear and the rotary element.

56. A machine of the class described, comprising in combination, a frame; a bundle support stationary relative to the frame; an abutment adjustable relative to the support for locating the bundle in binding and tying position thereon; means below the support for gripping the end of 50 a wire; wire tying means; a wire guiding device reversible relative to the tying means for guiding the wire into the tying means before the wire is applied about the bundle; means for moving the guiding device about the bundle from a position 55 of rest adjacent one lower edge of the bundle to a position adjacent the opposite edge thereof for wrapping the wire about the successive faces of the bundle positioned on the support, and again guiding the wire into the tying means to overlap 60 the initial tie portion for intertwisting therein to form a tie; a drive shaft; a rotary element mounted on the drive shaft for actuating the wrapping means; a motor for actuating the drive shaft; means intermediate the rotary element 65 and the wrapping means for imparting two directions of movement to the wrapping means for each revolution of the drive shaft; and a clutch to disconnect the drive shaft from the motor at the completion of each revolution.

70. 57. A machine of the class described comprising, in combination, a bundle support; bundle positioning means; means for wrapping a band about the bundle; means for clamping the bundle during wrapping; means for tying the band after 75

- Wrapping; a drive shaft; a rotary element mounted on the drive shaft for actuating the wrapping means; a motor for actuating the drive shaft; means intermediate the rotary element 5 and the wrapping means for imparting two directions of movement to the wrapping means for each revolution of the drive shaft; and a clutch to disconnect the drive shaft from the motor at the completion of each revolution.
- 10 58. A machine of the class described comprising in combination, means for supporting a bundle, adjustable means cooperating with the support for properly positioning the bundle, means for engaging the bundle positioning means to prevent movement thereof during placement of the bundle, means for wrapping a band about the bundle, and means for releasing the bundle positioning means to release the bundle in the direction of said released bundle positioning means.
- 15 59. In a machine of the class described, means for supporting a bundle, adjustable means cooperating with the support for properly positioning the bundle, means for engaging the bundle positioning means to prevent movement thereof during the placement of the bundle, means for wrapping a band about the bundle, means for releasing the bundle positioning means, and means for forcing the wrapped bundle against the released positioning means and out of binding position.
- 20 60. In a machine of the class described, means for supporting a bundle, means for clamping the bundle on the support, releasable means for positioning and aligning the bundle on the support, said clamping means releasing the positioning means during the clamping of the bundle to permit removal of the bundle, means for binding and tying the bundle while clamped, and means for conveying the bundle out of the machine.
- 25 61. In a machine of the class described, means for supporting a bundle, releasable means cooperating with the support for properly positioning the bundle, means for engaging the bundle positioning means to prevent movement thereof during placement of the bundle; means for wrapping a band about the bundle, means for releasing said engagement means whereby the positioning means are released to permit removal of the bundle, means for forcing the wrapped bundle against the released positioning means and out of binding position, and means for returning the positioning means to its original position.
- 30 62. In a machine of the class described, a bundle support, releasable abutment means against which a bundle placed on the support may be thrust for proper positioning and alignment, means for engaging the abutment in aligned position to prevent movement thereof during placement of the bundle, means for binding and tying the bundle while so held, means for clamping the bundle during the binding thereof and for releasing the bundle after the tying begins, and means for releasing the abutment means.
- 35 63. In a machine of the class described, a bundle support, bundle abutment means swingable above the support, locking means for the abutment means mounted on the support, and a trip 70 also on the support for holding the locking means in the releasing position.
- 40 64. A machine of the class described, comprising, in combination, a frame; bundle supporting means; a carrier; means on the carrier for guiding the lead of a wire below the plane of the
- supporting means; revoluble arms mounted on the frame and connected with the carrier; and means mounted on the frame for actuating said arms to cause said wire guiding means to move in an arcuate path over the supported bundle for enclosing a supported bundle with the wire and convexly tensioning the wire so that it presses inwardly and tightly against three faces of said bundle.
- 45 65. In a bundle tying machine; a bundle support; wire tying means; a carrier oscillatory relative to the tying means; means mounted on said carrier in spaced relation, for guiding the wire into the tying means, in each direction of movement thereof; means for mounting the carrier for movement in an arcuate path about the sides of a bundle placed on the support for the binding thereof; two of said wire guiding means providing means whereby the banding lead of the wire passing therebetween transfers from one to the other for the convex tensioning thereof as the carrier is actuated to bind the bundle; a motor; means intermediate the motor and the carrier comprising a sector gear and pinion, a drive shaft, a rotary element mounted on the drive shaft, and a reversing bar connecting the sector gear and the rotary element for oscillating the sector gear and the carrier.
- 50 66. A bundle tying machine comprising, in combination, a frame; means for gripping the end of a wire; wire guiding means on the frame; bundle supporting elements stationary relative to the frame and providing a passageway for a wire; wire tying means adjacent the gripping means; an abutment adjustable toward and from the gripping means for locating a bundle in proper tying position on the supporting elements; means for clamping a bundle so located; means on the frame for delivering the wire in tensioned state; a bundle binding device oscillatable in a vertical plane intermediate said supports for wrapping the tensioned wire first into tying position within the tying means and then completely about a bundle positioned on the support and again into the tying means whereby the initially wrapped tie portion therein is overlapped in the plane in which the wire was wrapped; means for oscillating the device; a bundle clamp; means for actuating the clamp to clamp the bundle during movement of the device and; means for actuating the wire tying means for intertwisting the overlapped portions to form the tie.
- 55 67. A bundle tying machine comprising, in combination, a frame; bundle supporting elements stationary relative to the frame and providing a passageway for a wire; wire guiding means on the frame in a plane extending through said passageway; means for gripping the end of a wire; a rotary slotted twister below the support with its slot in register to receive the wire in said plane; an abutment adjustable toward and from the twister for locating a bundle in proper tying location on the supporting elements; means on the frame for delivering the wire in tensioned state; a bundle binding device oscillatable in said plane intermediate said guiding means and the gripping means for wrapping the tensioned wire first into tying position within the slot of the twister and then completely around a bundle positioned on the support and again into the slot of the twister whereby the initially wrapped tie portion therein is overlapped; a motor; means intermediate the motor and the binding device comprising a rack and pinion, a drive shaft, a rotary element mounted on the drive shaft, and a

reversing bar connecting the rack and the rotary element for oscillating the sector gear and the binding device; and means for actuating the twister for intertwisting the overlapped portions 5 to form a tie for securing the band about the bundle.

68. A bundle tying machine comprising, in combination, a frame; bundle supporting elements stationary on the frame and spaced to provide a passageway for a wire; means for gripping the end of a wire; means for tying the wire; an element oscillatable relative to the tying means in a vertical plane intermediate said spaced supports; wire guiding means on the element between which the wire passes and normally positioned with the lead of the wire disposed under the support; means for delivering the wire under tension to the wire guiding means; means against which a bundle is placed directly into tying location on the support above the lead of the wire; means for clamping the located bundle; means for oscillating the element whereby the wire guiding means move from below the support for wrapping the tensioned wire first into the tying means and then progressively about the entire periphery of the bundle and again into the tying means, whereby the initial tie portion of the wire disposed in said means is overlapped therein in the plane in which the wire was wrapped; means for actuating the tying means; means for severing the tied band about the bundle from the lead of the wire extending to the guiding means; a drive shaft; a motor for actuating said drive shaft; means mounted on said shaft for actuating the gripping means, the tying means and the guiding means in order of sequence; means on the shaft for actuating the clamping means simultaneously with the initial actuation of the guiding means; and a clutch adapted to disconnect the motor from the shaft at the completion of each binding operation.

69. A machine for tying bundles, comprising, in combination, spaced bundle supporting elements; a rotary slotted twister disposed intermediate said elements; an abutment adjustable toward and from the twister for locating a bundle in proper tying location on the supporting elements; a device for wrapping a wire about a bundle in a plane to register with the slot of said twister; means for actuating said device in an arcuate path in opposite directions of travel past said twister for disposing tie portions of the wire in overlapping parallel relation within the slot of the same; and means for actuating the twister to intertwist the overlapped portions of the wire therein.

70. A machine of the class described comprising, in combination, a frame; wire guiding means on the frame; wire wrapping means movable in alignment with said guiding means for drawing the wire therefrom and wrapping the wire into band formation about a bundle; an automatic wire tensioner and wire slack take-up device for delivering the wire under tension to the wrapping means comprising a pivoted arm; means urging said arm to swing in one direction and resisting swing thereof in the opposite direction; and wire feed-retarding means mounted on the free end of the arm to control the tension and feed of the wire leading to the wrapping means in any position of said means.

71. In a machine of the class described, a frame; wire guiding means on the frame; wire wrapping means on the frame movable relative 75 to the wire guiding means for wrapping the wire

leading therefrom into band formation about a bundle; an automatic wire tensioner and slack take-up device for delivering the wire under tension to the wire guiding means comprising an arm pivoted on the frame; a spring adjustably connected to the frame whereby its tension may be varied, said spring also being connected with the arm; and wire feeding pulleys mounted upon the free end of the arm over which the wire passed.

72. A machine of the class described comprising, in combination, a frame; wire tensioning means on the frame; a bundle support; bundle binding means operative to form a tensioned wire band about a bundle positioned on the support within the path of travel of said binding means; and wire controlling means operative to control the tension of the wire extending between the tension means and the binding means comprising a pivoted arm urged to swing in one direction and resist swinging in the opposite direction and a plurality of wire guiding pulleys on the free end of the arm over which the wire is successively passed.

73. A machine of the class described comprising in combination, a frame; a bundle support; means for adjustably clamping a bundle on the support; means on the frame for guiding a wire from a source of supply to the binding means; wire guiding instrumentalities co-adjacently mounted in a vertical plane on one side of an oscillatable member and adapted for cooperatively receiving and wrapping the guided wire progressively about the respective faces of the bundle during movement of said member in said vertical plane; and wire controlling means operative on the wire between the source of supply and the binding means comprising an instrumentality movable in opposite directions independently of the binding means and a plurality of wire guiding and feed-retarding means over which the wire is successively passed, said wire feed-retarding means being carried by said instrumentality.

74. In a wire tying machine, a wire twisting device; means reversible relative to said device for effecting passing of the wire about a bundle to be tied and overlapping portions thereof in the twisting device, said reversible means including a pair of rotative guides between which the wire transfers so that it will be convexed for effecting tight hugging of the wire against the sides of the bundle; a motor; a shaft driven by said motor; a rotary element on the shaft; means including a rack and pinion driven by said rotary element for reversing and actuating said passing means; and means for rotating the twisting device to tie the wire passed about the bundle.

75. In a wire tying machine, a slotted wire twisting device; means for tensioning the wire; means reversible relative to said device for effecting passing of the wire about a bundle to be tied and overlapping portions thereof in the slot of said device, said reversible means including a pair of rotative guides between which the wire transfers so that it will be convexed to cause the wire to lie flatly and tightly against the sides of the bundle; a motor; a shaft driven by said motor; a rotary element on the shaft; means including a rack and pinion driven by said rotary element for reversing and actuating said passing means; and means for rotating the twisting device to tie the wire passed about the bundle.

76. In a wire tying machine, a slotted wire twisting device; means for tensioning the wire;

means reversible relative to said device for effecting passing of the wire about a bundle to be tied and overlapping portions thereof in the slot of said device, said reversible means including a 5 pair of rotative guides between which the wire transfers so that it will be convexed to cause the wire to lie flatly and tightly against the sides of the bundle; a motor; a shaft driven by said motor; a rotary element on the shaft; means including a rack and pinion driven by said rotary element for reversing and actuating said passing means; means for rotating the twisting device to tie the wire passed about the bundle; means for severing the tied wire from the wire 10 beyond the twisting device; and means for moving the bundle and releasing the tie.

77. In a wire tying machine, means for supporting a bundle; a slotted wire twisting device disposed below the support; means oscillatory 20 relative to said device for effecting passing of the wire about a bundle to be tied and overlapping portions thereof in the slot of said device, said oscillatory means including a pair of rotative guides between which the wire transfers 25 so that it will be convexed for effecting tight hugging of the wire against the sides of the bundle; a motor; a shaft driven by said motor; a rotary element on the shaft; means including a rack and pinion driven by said rotary element 30 for oscillating said passing means; means for rotating the twisting device to tie the wire passed about the bundle; means for severing the tied wire from the wire beyond the twisting device; means for moving the bundle and releasing the tie; and means for maintaining the wire in tension during oscillation of the passing means.

78. In a wire tying machine, means for supporting a bundle; means disposed below the support for tying a wire; means oscillatory relative 40 to said tying means for effecting passing of the wire about a bundle to be tied, said oscillatory means including a pair of rotative guides between which the wire transfers so that it will be convexed to cause the wire to lie flatly and tightly against the sides of the bundle, and to overlap the wire within the tying means; a motor; a shaft driven by said motor; a rotary element on the shaft; means including a rack and pinion driven by said rotary element for 45 oscillating said passing means; means for actuating the tying means to tie the wire passed about the bundle; means for severing the tied wire from the wire beyond the tying means; means for moving the bound bundle out of the 50 machine; and means for maintaining the wire in tension during oscillation of the passing means.

79. A bundle binding machine having a bundle support, comprising an oscillatory element, a 60 wire twister below the support, two wire guides on said oscillatory element, and means for actuating said element whereby a wire is directed through the twister to a position substantially in the plane of the support, then around the bundle 65 and back through the twister, said wire being disengaged from one guide and directed by the other as the element moves around the bundle.

80. In a bundle tying machine, means for supporting a bundle in a fixed location, means for 70 clamping the bundle so located, means for passing a wire around the fixedly located bundle with one portion of the wire overlapping another portion of the wire, said overlapping portions being parallel and being disposed in a vertical plane 75 parallel to a side of the bundle at the side of the

bundle, means for twisting together the overlapping portions of the wire; a drive shaft, a rotary element on the said shaft for actuating the passing means and the twisting means in order of sequence, and means on said shaft for actuating the clamp simultaneously with the initial actuation of the passing means.

81. In a bundle tying machine, means for passing a wire around the bundle to be tied without sliding the wire across a surface or edge of the 10 bundle, a device adapted to be rotated to twist together overlapping portions of the wire, means for rotating the device, and means for imparting two directions of movement to the means for passing the wire around the bundle for each operation of the twisting device.

82. In a bundle tying machine, means for effecting passing of wire in one direction about an object to be tied, means for gripping the wire at the end of its movement around the bundle and 20 means for subsequently passing the wire in the opposite direction whereby the wire is bent over and against the gripping means, a motor; a shaft driven by said motor, a rotary element on the 25 shaft, and means including a rack and pinion driven by said rotary element for actuating said passing means in said directions in each cycle of operation of the machine.

83. In a binding machine, means for clamping a binding wire, means for tensioning the wire, and 30 wire guide means interposed between the clamping and the tensioning means and movable orbitally to effect winding of the wire about an object to be bound, said guide means being positioned to contact the wire so as to flex the wire away 35 from the object and in the plane of the winding during its entire orbital movement about the object, and means comprising a drive shaft; a rotary element on the shaft, and mechanism including a rack and pinion driven by said rotary 40 element for orbitally moving the guide means in opposite directions.

84. A bundle binding machine comprising a bundle support, a rotary wire twister located below the plane of the support, a device for effecting passing of a wire first into the twister, then to a position substantially in the plane of the support, and finally around a supported bundle and back into the twister in a given plane to provide portions of the wire overlapped within the twister, 45 means for rotating the twister to form a tie, means for imparting oscillatory movement to the device, said device passing the wire into the twister in one direction of movement of the device and about the bundle and again into the twister in the 50 opposite direction of movement.

85. A bundle binding machine comprising, a bundle support; bundle binding means; two guides carried by said means; and mechanism for actuating said means whereby the lead of a wire is 60 guided to a position substantially in the plane of the support for ready application about a bundle and thereafter wrapped completely about the bundle, said wire being guided into said position by one guide and disengaged therefrom and directed by the other guide as the means moves about the bundle.

86. In a bundle binding machine, a frame; a support stationary relative to the frame; means for passing a wire about a bundle located on the 70 support; means for tying the wire passed around the bundle; means movable toward the support for clamping the bundle comprising a guide bar slidably mounted on the support; a clamping bar secured to the guide bar; a cam; a pivotally 75

mounted arm having a roller contacting said cam; a resilient connection between the arm and the guide bar; a rotatable shaft mounting said cam; and means for driving the shaft whereby the 5 clamp effects the clamping of a bundle during the movement of the wrapping means irrespective of the size thereof, within the yieldability of the resilient connection.

87. A bundle binding machine comprising, an 10 oscillatory element; a slotted rotary wire twister; two guides on said oscillatory element; and means for actuating said element whereby a wire is directed into the slot of the twister around a bundle and back into the slot of the twister to overlap the wire therein, said wire being disengaged from one guide and wrapped tightly 15 against three sides of the bundle by the other guide as the element moves about the bundle; said actuating means comprising a motor; a shaft driven by said motor; a rotary element on the shaft; and means intermediate said rotary element and said oscillatory element comprising a rack and pinion for oscillating said oscillatory element.

88. A bundle binding machine comprising, an 20 oscillatory element; a slotted rotary wire twister; two guides on said element; and means for actuating said element whereby a wire is directed into the slot of the twister around a bundle and back into the slot of the twister, said wire being disengaged from one guide and convexly tensioned and directed by the other guide to effect tight 25 hugging of the wire against three sides of the bundle as the element moves about the bundle; said actuating means comprising a motor; a shaft driven by said motor; a rotary element on the shaft; and means intermediate said rotary element and said oscillatory element comprising a rack and pinion for oscillating said oscillatory element.

89. A bundle binding machine comprising, an 30 oscillatory element; a slotted rotary wire twister; two guides on said element; means for actuating said element whereby a wire is directed into the slot of the twister around a bundle and back into the slot of the twister, said wire being disengaged from one guide and convexly tensioned and directed by the other guide to effect tight 35 hugging of the wire against three sides of the bundle as the element moves about the bundle; means for clamping the bundle as the wire is wrapped about the bundle; said actuating means comprising a motor; a shaft driven by said motor; a rotary element on the shaft; means intermediate 40 said rotary element and said oscillatory element comprising a rack and pinion for oscillating said oscillatory element and means on the shaft for actuating the bundle clamping means simultaneously with the initial actuation of said element.

90. A bundle binding machine comprising, an 45 oscillatory element; a slotted rotary wire twister;

two guides on said element; means for actuating said element whereby a wire is directed into the slot of the twister around a bundle and back into the slot of the twister, said wire being disengaged from one guide and convexly tensioned and directed by the other guide to effect tight hugging of the wire against three sides of the bundle as the element moves about the bundle; means for delivering and retracting the wire under tension during the oscillation of said element; means for actuating the twister to form a tie; and means for ejecting the tied bundle from the machine. 5

91. A bundle tying machine comprising, a fixed bundle support; oscillatory means for guiding the lead of a wire below the support preparatory to 10 the binding of a bundle; and means for moving the wire guiding means whereby the wire is wrapped entirely around a bundle placed on the support over said lead of the wire; said latter means being capable of returning the wire guiding means to the initial position preparatory to 15 the binding of another bundle.

92. A bundie-binding machine comprising means for holding a bundle, a carrier adjacent 20 said bundle holding means, means for oscillating said carrier for guiding the wire to a position below the plane of the bundle holding means in one direction of movement thereof and moving the wire into band formation about all faces of the bundle in the opposite direction of movement 25 thereof without sliding the wire across the face or edge of the bundle, means for automatically cutting said wire, means to fasten the wire ends together and means for securing the free end of the wire for the next operation. 30

93. In a bundle-tying machine, the combination of means to hold a bundle, oscillatory means to carry a tie wire around the bundle, a roll over which the tie wire passes to place a stress in said tie wire so that it will be convexed toward the 35 bundle, means to sever the tie wire, means to secure the ends of the tie together, and means for oscillating said oscillatory means for guiding the wire to a position below the plane of the bundle holding means in one direction of movement 40 thereof and moving the wire into band formation about all faces of the bundle in the opposite direction of movement thereof.

94. In a bundle tying machine, the combination of a support, means to secure a bundle thereon, an oscillatory carrier to carry a tie wire around the bundle, means to convex the tie wire, means to sever the tie wire, means to secure the tie ends together, so that the tie will be convex inwardly toward a face of the bundle when cut from the 50 bundle, and means for oscillating said carrier for guiding the wire to a position below the plane of the bundle support in one direction of movement thereof and moving the wire into band formation about all faces of the bundle in the opposite direction of movement thereof. 55
